UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC COMPANY, A CORPORATION OF ILLINOIS.

TELEPHONE SYSTEM.

Application filed September 16, 1905. Serial No. 278,816.

To all whom it may concern:

Be it known that I, TALBOT G. MARTIN, a citizen of the United States of America, and resident of Chicago, Cook County, Illinois, 5 have invented a certain new and useful Improvement in Telephone Systems, of which the following is a specification.

My invention relates to telephone systems and more particularly to telephone systems 10 in which means are provided for enabling the calling subscriber to establish connection with the called subscriber's line without the assistance of a switchboard operator, although in this particular case, more 15 specifically considered, it contemplates certain improvements whereby a subscriber of an automatic telephone exchange may use his calling device for obtaining connection automatically with the line of a subscriber 20 of a manual exchange, and may then signal the called subscriber in the usual way. My invention also relates to automatic telephone apparatus and systems in which the current both for talking and switching and signaling 25 purposes is all supplied from the exchange or central station, as, for example, by means of batteries from which the talking and switching current is derived, and ringing-generators from which the current is obtained 30 for ringing the bells at the subscribers' stations. In this respect, my invention is in the nature of an improvement on the common battery automatic telephone system disclosed in my prior application, 35 Serial No. 258,508, filed May 2, 1905. Still more specifically considered, my invention contemplates certain improvements in automatic telephone switching apparatus whereby a subscriber of the common battery auto- 40 matic telephone system may establish connection with the line of a manual switchboard exchange of a particular type or character, as will hereinafter more fully appear.

To the foregoing and other useful ends, 45 my invention consists in matters hereinafter set forth and claimed.

In the accompanying drawings, Figure 1 is a diagram of a cord-circuit A, and of two 50 sub-stations #620 and #300 of a manual system, of a type in connection with which I have elected to illustrate my invention.

Figs. 1 and 2 taken together illustrate dia- 55 grammatically the switches and apparatus brought into play when an automatic sub-

scriber #220 is connected with a manual subscriber #620, a "first-selector" being represented at C to the left of line X—X, and a "connector" at D to the right of the same line.

Fig. 3 is a perspective diagram of the "first-selector" C, and Fig. 4 of the "connector" D.

Referring to Fig. 1, the sub-station #620, like all other sub-stations of the manual system to which said station belongs, is provided with a ringer 2 and a condenser 3 in the ringing-circuit, and with a transmitter 4 and a receiver 5 in the talking-circuit, and a retardation-coil 6 in the battery-circuit. Each subscriber's line terminates in the armatures of a cut-off-relay, as do the line-conductors 10 and 11 of the above sub-station #620 which terminates in the cut-off-relay-armatures 12 and 13. In order to 70 make clear the construction of the cord-circuit A, it will be best to follow the steps of the manual subscriber at sub-station #300 while he obtains connection with the manual sub-station #620. In making the call, the 75 subscriber at the former station removes his receiver 14 from the switch-hook 15 and thereby connects the two contact-points 16 and 17 with said hook when it rises. At once the line-lamp 18 becomes illuminated 80 as the direct result of the energizing of the line-relay 19, by a current that flows from ground-terminal G through the armature 20 and the line-conductor 21, through the retardation-coil 22 and the switch-hook 15, 85 the transmitter 23, the line-conductor 24, then through the armature 25, conductor 26, line-relay 19 and conductor 27 to the non-grounded terminal of the battery B. When the armature 28 of said line-relay is at- 90 tracted, a circuit is closed from the battery B, through the line-lamp 18 and the ground-terminal G¹, by way of a contact-point 29 and the armature 28. The manual operator then inserts the answering plug 30 into the 100 jack 31, and thereby closes another energizing circuit through the cut-off-relay 8, from the ground-terminal G², through the cut-off-relay 8, the conductor 32 and jack-sleeve 33, conductor 34 and supervisory-relay 35, 105 thence to the non-grounded terminal of the battery B to the grounded terminal G³. When the cut-off-relay attracts its armatures, the circuit through the line-coil 19 is opened at the point 36, and when the armature 28 110

falls away from the contact-point 29, the energizing circuit through the lamp 18 is also broken and the light is extinguished. At the same time that the cut-off-relay is 5 energized, the supervisory-relay 35, being in series with the former, is also energized. As soon as the cut-off-relay-armatures 20 and 25 close with the contact-points 37 and 38, respectively, a second supervisory-relay 39 10 is energized by a current that passes from the non-grounded terminal of the battery B through the supervisory-relay 35, conductors 34 and 32, armature 25, conductor 24, the transmitter 23 of the sub-station #300, 15 switch-hook 15, retardation-coil 22, conductor 21, armature 20, contact-point 37, conductor 41, and tip-spring 42 of jack 31, thence through conductor 7 and supervisory-relay 39 to the grounded terminal G³ of the 20 battery B. The two supervisory-relays thus energized will remain so as long as the sub-station #300 is in electrical connection with the cord-circuit A. The central operator then, by means of a cam, throws the cam-springs 43 and 44 into contact with the 25 contact-points 45 and 46, respectively, thereby placing the receiver 47 across the calling subscriber's line by means of the conductor 48 on one side, and the conductor 49 on the other. The operator will then speak in the transmitter 50 and inquire of the calling subscriber the number desired. The number 620 being given, the operator will first test the line #620 by striking the sleeve 51 of 30 the jack 52 with the tip 53 of the plug 54. If the line does not test "busy", in a manner that will be hereinafter described, the operator will insert said plug in the jack 52. As 35 soon as this is done, the cut-off relay 55 is energized by a current that passes from the non-grounded terminal of the battery B¹ to the ground-terminal G⁴, through the cut-off-relay 55 and conductor 56, jack-sleeve 51, contact-point 58, conductor 59, supervisory-relay 40 60 to the non-grounded terminal of the battery B¹. The supervisory-relay being in series with the cut-off-relay 55, the armatures of the former are attracted and the contacts 61 and 62 are drawn against the contact-points 63 and 64, respectively. As soon as 45 the cut-off-relay 55 is energized, the armatures 12 and 13 are drawn into contact with the contact-points 66 and 67, respectively, and the called subscriber's line is then extended to the jack 52 through the armatures 12 and 13 and the contact-points 66 and 67 50 with which the former are engaged. The manual board operator will then, by means of a key, press the springs 68 and 69 against the contact-points 70 and 71, respectively. Ringing-current will then be sent through the ringing apparatus of the sub-station #620 from the ringing-generator R through the contact-point 70, the spring 68 and the plug-tip 53, conductor 72, contact-point 67, armata-

ture 13, conductor 11, condenser 3, switch-hook 73, ringer 2, thence through the line-conductor 10, armature 12, contact-point 66, conductor 56, jack-sleeve 51, spring 69 and contact-point 71, retardation-coil 74, conductor 75^a, through the battery B¹ to the grounded terminal G³, to ground G⁵ and back to the ringing-generator R. The subscriber at sub-station #620, upon hearing the bell ring, will answer by removing his receiver 5 from the switch-hook 73, which latter on rising places the contact-points 75 and 76 in electrical connection. As soon as the said points are connected, and after the operator restores the springs 68 and 69 to their normal position against the contact-points 58 and 77, battery-current for talking purposes passes through the called subscriber's transmitter from the non-grounded terminal of battery B¹, through the supervisory-relay 60, conductor 59, contact-point 58, spring 69, jack-sleeve 51, conductor 56, armature 12, conductor 10 and transmitter 4, through the switch-hook 73, retardation-coil 6 and conductor 11, thence through the armature 13, conductor 72, jack-tip-spring 78, spring 68, contact-point 77, conductors 79, 62 and 80, supervisory-relay 81 to the grounded terminal G³ of battery B¹. The subscriber #300 being now connected with the subscriber #620, the voice-currents will travel back and forth over the following circuit: from the transmitter 4 of the sub-station #620, over the conductor 10, through armature 12, the jack-sleeve 51 and spring 69, conductor 59 and condenser 82, the conductor 34, jack-sleeve 33, and then over the conductors 32 and 24, through the transmitter 23 of sub-station #300, the switch-hook 15, receiver 14, conductors 21 and 41, thence through the tip-spring 42, the conductor 7, condenser 83, conductors 80, 62 and 79, contact-point 77, spring 68, plug-tip 53 and conductors 72 and 11, receiver 5, through the switch-hook 73 and again to the transmitter 4. When the manual subscribers are through talking, if the subscriber at sub-station #300 returns his receiver 14 to the switch-hook 15, the latter by the weight of the former will be drawn away from the contact-points 16 and 17, thereby opening the energizing circuit through the supervisory-relay 39. As soon as the armature of this relay falls to its normal position in contact with the contact-point 84, a circuit is closed through the supervisory-lamp 85, from the grounded terminal of battery B, through the armature 86, the contact-point 84, and the supervisory-lamp 85, through the armature 87, and thence through the contact-point 88 to the non-grounded terminal of battery B. Said lamp will then become lighted and the central operator will know that the subscriber is through talking. The operator will then remove the plug 30 from the jack 31 and

thus break the circuit through the supervisory relay 35 and cut-off-relay 8. The armatures of the latter will then return to their normal positions against the contact-points 36 and 89, respectively, and the armature 87 of the former leaves the contact-point 88, thus destroying the circuit through the lamp 85. Again, as soon as the subscriber at sub-station #620 restores his receiver, the energizing-current through the supervisory-relay 81 ceases to flow, and the armature 90 engages the contact-point 91. A circuit is thereby closed through the supervisory-lamp 92 from the grounded terminal of battery B¹, through the armature 90, the contact-point 91 and the lamp 92, through the conductor 61 and contact-point 63 to the non-grounded terminal of the battery B¹. The supervisory-lamp will then be lighted, and the operator will understand that the sub-station #620 is out of use, and will then remove the plug 54 from the jack 52 and thereby open the circuit through the cut-off-relay 55. Then the armatures 12 and 13 return to their normal positions against contact-points 93 and 94.

The automatic telephone sub-stations, such as the one represented in Fig. 2, are of the usual type, and are each provided with the usual necessary mechanical and electrical details. Among said details there is, for instance, a receiver 100 in the secondary circuit in series with the secondary winding 101 of the induction-coil 102. The normal position of said receiver is on the switch-hook 103, and the latter when permitted to rise opens a normally-closed circuit through the ringer 104 at the springs 105 and 106, and at the same time closes the primary-circuit-springs 107 and 108 and the ground-circuit-springs 109 and 110. In series with said ringer-springs and with the ringer apparatus there is a condenser 111. Whenever the receiver is replaced on the hook-switch, the latter on its downward stroke forces into connection the so-called release-springs 112, 113 and 114 by means of a short arm-like member 115. In the primary circuit, the transmitter 116 is in series with the primary winding 117 of the induction-coil 102, and with the two primary-circuit-springs 107 and 108. Said primary circuit terminates at the calling device in two contact-points 118 and 119 which are normally in contact with the two springs 120 and 121, respectively. The latter constitute the terminals of the line-conductors 122 and 123 that connect the substation #220 with the central exchange. In signaling, the button 124 is the means by which the signaling-spring 125 is shifted from normal engagement with the contact-point 126 into engagement with the contact-point 127.

65 The "first-selector" shown is one of a

well-known or suitable type. A well-known type is shown in Patent No. 815,321, granted March 13, 1906, to Keith, Erickson & Erickson, and one of this character is represented at C in Figs. 2 and 3. This "selector" receives the subscriber's vertical and rotary line-conductors 123 and 122, respectively. The said conductors terminate in the side-switch-wipers 130 and 131, as shown. Bridged across said side-switch-wipers are the vertical and rotary line-relays 132 and 133. These relays (Fig. 3) control the calling mechanism of the "first-selector" C, through the line-relay-armatures 134 and 135, and through the line-relay-springs 136, 137 and 138. After a "first-selector" 70 trunks to or makes connection with a "connector," said "first-selector" can only be restored by means of a back-release-relay 139 and the back-release-relay-springs 140 and 141, as hereinafter described. When an automatic subscriber calls the subscriber #220, the connection is established over the normal-conductors 142 and 143 that lead from the "connector-banks." At the same time, 75 the calling "connector-private-wiper," in a manner to be described, connects the private-normal 144 with the ground, and thereby completes an energizing circuit through the so-called bridge-cut-off-relay 145 of the "first-selector." Said bridge-cut-off-relay 80 has under its supervision three springs 146, 147 and 148. Through the first two, the bridging circuit through the line-relays 132 and 133, to which reference has been made, is completed. Therefore, whenever the bridge-cut-off-relay 85 is magnetized, the springs 146, 147 and 148 are forced apart by the bridge-cut-off-relay-armature 149, and the said bridging circuit is opened. 90 The object in removing this bridge is to prevent the short-circuiting of voice-currents when two subscribers are talking. The short-circuiting circuit would be from the line-conductor 123 through the side-switch-wiper 130, the vertical-line-relay 132 and 95 the bridge-cut-off-relay-springs 147 and 146, through the rotary-line-relay 133 and the side-switch-wiper 131 to the line-conductor 122. Whenever the vertical-line-relay 132 100 is energized, the line-relay-springs 136 and 137 are brought together by the armature 134, and a circuit is closed that energizes the vertical-magnet 150. Said magnet is composed of two coils 151 and 152, and its 105 office is to operate the shaft 153 in a vertical or longitudinal direction. The shaft has secured to it a number of circular ratchet-teeth 154 that serve for various purposes. Said circular teeth are used by the vertical-pawl 155 as a means for raising the shaft. The said pawl is pivotally supported at the 110 end of the vertical arm member 156 formed on the vertical-armature 157, and carries attached to its rear portion one end of a 115 120 125 130

spring 158, the other end of which latter is attached to the vertical-arm. Therefore, the said pawl is given a constant tendency to fall forward against the circular ratchet-teeth 154. Said circular teeth, in connection with the locking-arm 159 on the so-called double-dog 160, act as a locking device that holds the shaft when raised to a new position. Said locking-arm is normally held away from said shaft by a link 161 known as the release-link which locks the double-dog in its normal position. The said link is made of thin spring material and is fastened at one end to the armature 162 of the release-magnet 163. The free or locking end of this link has stamped out of it a square section, leaving an aperture 164 that receives a lug 165 on the double-dog when the switch is in its normal or released condition. The operation of these mechanical parts may be described as follows: Each time the vertical-magnet 150 is energized, the vertical-armature 157 is attracted, carrying with it the vertical-arm 156. At each upward stroke the vertical-pawl 155 engages with one of the circular teeth 154 and raises the shaft one step. At the first step the link 161 is lifted from engagement with the lug 165 by an L-shaped piece 170 attached to the vertical-arm 156. As soon as the double-dog is released, the double-dog-retracting-spring 171 draws the locking-arm 159 into engagement with the circular teeth (the double-dog being mounted on pivots 491), so that when the vertical-pawl returns to its normal position, the shaft is retained in the new position by said locking-arm. It will be understood that the double-dog-retracting-spring 171 is properly adjusted to perform the work for which it is designed, and has one terminal fastened to the switch-frame and the other to the double-dog. After the shaft is once raised, the circular teeth act as a shaft-support whenever said shaft is rotated, but before any rotation can take place the private-magnet 172 must be energized. The private-armature 173, which is supported from the private-magnet-frame, works in a vibratory manner about a horizontal axis that passes through the supporting points 174 and 175. Said armature is formed with a forwardly-projecting arm 176 having two flat surfaces in an approximately horizontal plane. The said arm has a short length 177 at its forward extremity bent downwardly at right-angles thereto. This arm 176 carries certain other mechanical details, viz: a lateral arm 178 designed to control the relation of the private-springs 179, 180 and 181, and a tooth-escapement which includes two flexible springs 182 and 183, each of which is riveted at one end to the arm 176, one on the upper side and the other on the lower. The upper spring is straight and has formed

near its forward end two downwardly-extending tooth projections 184 and 185, while the under spring is bent downwardly and then toward the front. This double angle on the lower escapement-spring is so designed that the latter may clear the bent portion 177 of the private-arm 176 against which it rests with some degree of tension, and so that there may be space in front of said bent portion to receive two other tooth-shaped and upwardly-projecting pieces 186 and 187 formed on the forward end of this escapement-spring, and which are situated near the upper teeth and slightly to the rear thereof. A retracting-spring 188, which has one end attached to the private-armature and the other to the switch-frame, holds the former normally away from the private-magnet-pole-piece. In conjunction with the escapement above described, there is an escapement-finger 189 which constitutes the right extremity of the side-switch-arm 190. Said finger is normally retained behind the rearmost tooth of the lower escapement-spring. The side-switch-arm has near the base of said escapement-finger a forwardly-bent lug 191, the purpose of which is to limit or control the stroke of the side-switch-arm when the side-switch passes from the first to the second position, at which time it strikes the cam-piece 192 located on the shaft. The side-switch-arm may be made to oscillate about pivotal supports 193 and 194 located near its middle, and said arm carries to the left of its center a rearwardly-projecting member 195 pivotally connected at its extremity with a link 196. The other end of said link is bifurcated and engages the lower extremity of the downwardly-projecting arm 197 of the double-dog. Very near the left extremity of the side-switch-arm there rises a shaft 198 which supports the side-switch-wipers 199, 200, 130 and 131. These wipers are rigidly secured to the side-switch-arm and as a whole may be made to assume one of three positions. In each of said positions each of these wipers engages one of a series of contact-points 201, 202 and 203, 204, 205 and 206, 207, 208 and 209, 210, 211 and 212. The side-switch-arm with all its associated parts constitutes the well-known side-switch arrangement which, when in the first or normal position, retains the side-switch-wipers, in the order named, in engagement with the contact-points 201, 204, 207 and 210, respectively. In the second position these wipers, in the same order, are in engagement with the contact-points 202, 205, 208 and 211, respectively, and when in the third position with the contact-points 203, 206, 209 and 212, respectively. The means for moving the side-switch-finger 189 in a forward direction consists of a retracting-spring 213 which is fastened by one end to

the switch-frame and by the other to the side-switch-arm 190. When the private-magnet is energized once, the private-armature is drawn down momentarily, and then restored. By this operation the escapement-finger 189 passes first from behind the tooth 186 onto the tooth 185, at the downward stroke of the private-armature, and from behind the latter tooth upon the return stroke. As soon as the escapement-finger 189 clears itself, the retracting-spring 213 draws the side-switch to the second position, and the motion is stopped by the lug 191 striking the cam 192. As soon as the side-switch-wiper 199 passes to the second position and, consequently, into contact with contact-point 202, the shaft is rotated. The rotating force is provided by the rotary-magnet 214 which is composed of two coils 215 and 216. The rotating mechanism consists of the rotary-armature 217, a circuit-interrupting-arm 218 that works in conjunction with two interrupter-springs 219 and 220, the rotary-armature-finger 221 that exercises certain controlling influences over the private-armature, and lastly the rotary-arm 222. This last arm carries pivotally attached to its forward end the so-called rotary-pawl 223. Said pawl has attached to its rear end a small coiled spring 224 the other end of which is fastened to the rotary-arm and which imparts to the rotary-pawl a constant forward tendency to engage with the longitudinal-ratchet-teeth 225. Said teeth are located on the larger diameter of the same member that carries the circular ratchet-teeth and, together with a locking-arm 226 on the double-dog, form the locking means that retains the shaft in any position to which it may be rotated. At each rotary step of the shaft the locking-arm 226 falls into engagement with one of the longitudinal-teeth. Said locking-arm and longitudinal teeth form the rotary locking means. When the rotary-armature is energized, the rotary-pawl 223 engages with the longitudinal-teeth 225, and the shaft is rotated until the rotary-armature 217 strikes the rotary-magnet-pole-pieces. The energizing circuit of the rotary-magnet passes through the interrupter-springs 219 and 220, and when the rotary-armature is attracted these springs are separated by the interrupter-finger 218. When the energizing circuit is broken, the rotary-armature is drawn to its normal position by the rotary-armature-retracting-spring 227. The shaft also carries two wipers 228 and 229 known as the line-wipers, which are separated from each other and from said shaft by suitable insulating material. Just above these line-wipers, the private-wiper 230 is secured in place and insulated from the shaft. Under the switch parts, and near the line-wipers, the line-terminal-contacts 231 and the private-terminal-contacts 232 are arranged in banks one above the other. The private-contact-terminals are each one electric conducting piece, but the line-contact-terminals are each made of two metallic pieces, one over the other and insulated from each other. When the shaft is raised and rotated, the wipers engage with the contacts of their respective banks, the private-wiper with those of the private-bank, and the line-wipers with those of the line-bank. The shaft also carries a coil-spring 233 against the tension of which the shaft is rotated. One end of the spring is secured to the shaft and the other to the guide or so-called normal-post 234. When the switch is in use, it may be released or restored by the energizing of the release-magnet 163. The release-link is then thrown forward, when the release-armature 162 is attracted, until it locks with the double-dog-lug 165. Then when the armature is drawn back after the release-magnet loses its magnetizing force, the double-dog is drawn away from the shaft 153. The shaft, if it has been raised and rotated, rests on the shaft-rest 235, and being left to the action of the coil-spring 233 it rotates on the shaft-rest until the stop-arm 236 strikes the guide-post 234. The shaft-rest then enters the channel 237 that traverses the circular teeth, and leaves the shaft to fall to its normal position by its own weight. There is a so-called normal-spring 238 that works between two contact-points 239 and 240, the position of which spring is controlled by the normal-arm 236. Whenever the shaft is raised, this normal-spring leaves the contact-point 239 and engages the contact-point 240. In this way, a guarding potential is thereby established at the "connector-private-banks," by way of the private-normal-conductor 144, whenever the switch-shaft is raised. It will be understood that the vertical-armature 157 vibrates about a horizontal axis that passes through two pivot-points 245 and 246 that support said armature on the switch-frame. Similarly, the rotary-armature vibrates in a vertical plane about the pivot-points 241 and 242, and the release-armature is supported from the pivots 243 and 244.

The "connector" may be of the type shown in Patent No. 815,176, granted March 13, 1906, to Keith, Erickson & Erickson. In general the "connector" is very similar to the "first-selector," and many of the mechanical operations of the former are brought about by exactly the same methods and through the same means as in the latter. For instance, the "connector" is provided with vertical and rotary line-relays 250 and 251 which, when energized, operate the machinery through the medium of their respective armatures 252 and 253, and a number of springs 254, 255, 256, 257 and 258. The ver-

tical motion of the shaft 259 is brought about by means of the vertical-magnet 260, the vertical-armature 261, the vertical-arm 262, the vertical-pawl 263, and the circular-teeth 264, as described in the case of the "first-selector." Said shaft is retained in its raised position by the locking-arm 265 of the double-dog 266, after the latter has been released from the release-link 267 by the L-shaped piece 268. This release occurs at the first vertical motion of the vertical-armature. The shaft, after being raised, is rotated by the energizing of the rotary-magnet 269, through the medium of the rotary-armature 270, the rotary-arm 271, the rotary-pawl 272 and the longitudinal-teeth 273. As in the "first-selector," the rotary-locking-arm 247 and the longitudinal-teeth 273 constitute the locking means for the rotary positions of the shaft. It will be noticed that there is a difference between the mechanical make-up of the "first-selector-rotary-armature" and that of the "connector." The former has an interrupter-finger and a rotary-armature-finger, while the latter has only one arm 271, namely, the rotary-arm. Therefore, the rotation of the "connector-shaft" does not take place automatically, as is the case with the "first-selector-shaft," but directly as a result of the operation of the calling device of the calling station. For instance, after the vertical-magnet 260 has raised the shaft a desired number of steps, the private-magnet 274 is then energized. The latter carries an armature 275 with a lateral arm 276 having charge of the private-springs 277, 278, 279 and 280, and there being a tooth-escapement similar to that described in connection with the "first-selector." Said private-armature carries four escapement-teeth 281, 282, 283 and 284 that work in conjunction with the escapement-finger 285 of the side-switch-arm 286. This latter—the side-switch-arm—is exactly the same as the side-switch-arm of the "first-selector" and is provided with the cam-lug 287, the arm 288 that holds the link 289 which meshes with the side-switch-releasing-arm 290 of the double-dog, and the side-switch-wipers 291, 292, 293, 294 and 295 supported on a shaft 249 rigidly fastened to the side-switch-arm 286. The side-switch of the "connector" is, therefore, the same as that of the "first-selector" with the exception that it carries five side-switch-wipers instead of four. When the private-magnet is energized, the side-switch passes to the second position, and the side-switch-wipers 291, 292, 293, 294 and 295, in their order, pass from engagement with the contact-points 296, 297, 298, 299 and 300 into engagement with the contact-points 301, 302, 303, 304 and 305, respectively. By the shifting of the side-switch-wiper 291 from contact-point 296 to contact-point 301, the local path of the electrical pulsations is changed from

the vertical-magnet to the rotary-magnet, so that upon the operation of the calling device, after the side-switch has shifted, the rotary-armature is attracted instead of the vertical-armature, but only once for each electric pulsation that traverses the circuit. Each time that the rotary-armature is attracted, the rotary-pawl engages with the longitudinal-teeth 273, just as was described in connection with the "first-selector," and the shaft is rotated step-by-step. The next time that the private-magnet is energized, after the shaft is rotated, the side-switch passes from the second to the third position, and the side-switch-wipers 291, 292, 293, 294 and 295 now pass into engagement with the contact-points 306, 307, 308, 309 and 310. It may be stated at this juncture that the "connector" is, more specifically considered, preferably of the type of common battery "connector" disclosed in my said former application, Serial No. 258,508, filed May 2, 1905. The "connector," unlike the "first-selector," is provided with only one set of bank-contacts 311, and with only one set of wipers, the line-wipers 312 and 313. On the shaft are also found the cam 314, the normal-arm 315, and the coil-spring 316. After the "connector" has been operated so that the shaft has been raised, and the wipers rotated into connection with bank-contact-points, the switch may be released by the energizing of the release-magnet 317. This latter is provided with an armature 318 that carries an elongated portion 319. When this armature is attracted by the release-magnet, the double-dog 266 is rotated about the pivots 320 and 321, so that the locking-arms 265 and 247 are withdrawn from the teeth on the shaft, and the side-switch driven back at the same time to its first position and locked there by the escapement-finger 285 which engages behind the tooth 281. The double-dog is locked by the link 267; but unlike the "first-selector," one end of the said link is secured to the switch-frame and the other end provided with the usual aperture 324 that catches the lug 325 of the double-dog and retains the latter, as above described. It is evident that when the locking-arms are removed from the shaft the latter will be rotated back toward its normal position by the tension of the coil-spring 316. The shaft-support 326 holds the shaft up until the normal-arm 315 strikes the guide or normal-post 327, at which instant said shaft-support then enters the channel 328, thus permitting the shaft to drop to its lowest position. In addition, the "connector" is provided with a differential-relay 329 having two windings 330 and 331. Said relay controls, through its armature 332, a circuit that passes through two springs 333 and 334. This differential-relay is so wound that if the two windings 330 and 331 be connected

- in multiple, so that the leads 335 and 336 are together, and the leads 337 and 338 are together, a flow of current from one set of said leads to the other will magnetize the relay.
- 5 Or if current passes through one winding alone, the relay will become magnetized. But should the coils be connected in multiple with the leads 336 and 337 together, and the leads 335 and 338 together, current on passing from one set of said leads toward the other through the coils, will not energize said relay, nor will it be magnetized if current passes from lead 337 to lead 338 when the leads 335 and 336 are connected. There
- 10 is also a retardation-coil 339, a back-release-relay-coil 340 with an armature 341, and two springs 342 and 343, and a ringer-relay 344. This latter, through its armature 345, shifts a number of circuits that include the ringer-relay-springs 346, 347, 348, 349, 350, 351, 352, 353 and 354.
- 15 For a clear understanding of my invention, it will be best to follow the steps of some one subscriber in making a call, and to study the relation of the various parts during the operation. Referring to Figs. 1 and 2, the automatic sub-station #220 may be connected with the manual sub-station #620, if the latter is not busy, by first removing the receiver 100 from the hook and pressing the button 355 of the calling device at the former station six times, and then pressing the button 356 once, the button 355 twice and the button 356 once, and the button 355 ten times and the button 356 once. When the receiver-hook rises, after the receiver is removed, the primary-circuit-springs 107 and 108 are pressed into contact with each other by the lug 357, and the
- 20 ground-springs 109 and 110 flex into engagement when the hook-projection 358 passes out of the way of the latter. The last two springs, upon coming into contact, complete a connection between the ground-post 359 and the ground-terminal G^6 through the following path: from the ground-terminal G^6 through the conductor 375, springs 109 and 110, and the conductors 376 and 377 to the ground-post 359. The
- 25 calling subscriber then proceeds to press the button 355 six times. Each time that said button is pressed the spring 121 is separated from the contact-point 119 and connected with ground at the ground-post 359. The result is that the vertical-line-relay 132 of the "first-selector" C is energized six times by pulsations of current which pass from the grounded terminal G^7 of the battery B^2 through the ground-terminal G^6 to the
- 30 ground-post 359, the spring 121 and vertical-line-conductor 123, thence through the side-switch-wiper 130, contact-point 207, conductor 378 and the vertical-line-relay 132, conductor 379, springs 147 and 148 and the conductors 380, 381 and 382 to the non-

grounded terminal of battery B^2 to the grounded terminal G^7 . Each time that the vertical-line-relay is energized, the armature 134 is attracted and the spring 136 pressed into contact with the ground-spring 137. In this way, a circuit is closed through the vertical-magnet 150 from the grounded terminal G^7 of the battery B^2 , through the ground-terminal G^8 , springs 137 and 136, conductor 383, private-springs 180 and 179 and conductor 384, the vertical-magnet 150, conductors 385, 386 and 382 to the non-grounded terminal of battery B^2 to ground G^7 . Each time that the vertical magnet is energized, the shaft is raised one step by the vertical-armature 157 and the pawl 155, and is retained at each advanced step by the locking-arm 159 which is thrown into working position after the vertical-armature has been attracted the first time. By six steps the shaft is raised so that the line-wipers 228 and 229 are put opposite the first contact of the sixth level of the line-bank 231, and the private-wiper correspondingly opposite the first contact of the sixth level of the private-bank 232. At the first step of the shaft, not only are the locking-arms released from their normal position, but the normal-arm 236 is raised away from the normal-spring 238, which latter breaks away from the contact-point 239 and closes in turn with the grounded contact-point 240. At the next operation the calling subscriber presses the button 356 of the calling device, thereby separating the spring 120 from the contact-point 118 and pressing said spring against the ground-post 359. A circuit is then closed momentarily through the rotary-line-relay 133 from the ground-terminal G^6 to the ground-post 359, and through spring 120 and rotary-line-conductor 122, thence through the side-switch-wiper 131, contact-point 210, conductor 387 and rotary-line-relay 133, conductor 388, bridge-cut-off-relay-springs 146, 147 and 148, conductors 380, 381 and 382 to the non-grounded terminal of battery B^2 to ground G^7 . The rotary-line-relay on being magnetized energizes the private-magnet by pressing the line-relay-spring 138 onto the ground-spring 137. The energizing circuit comprises the ground-terminal G^8 and the springs 137 and 138, conductors 389 and 440, the private-magnet 172, conductors 391, 386 and 382, and the battery B^2 to ground G^7 . As soon as the private-magnet attracts its armature, the side-switch passes to the second position and is then stopped by the cam-lug 191 striking against the cam 192. As soon as this occurs, the side-switch-wiper 199 closes connection with the side-switch-contact-point 202, thereby completing a circuit through the rotary-magnet 214, from ground-terminal G^8 to the contact-point 202, through side-switch-wiper 199, conductor 392, through

one of the rotary-magnet-coils 216 and the interrupter-springs 219 and 220, thence through the second magnet-coil 215 and over the conductors 385, 386 and 382 to the 5 non-grounded terminal of the battery B² to ground G⁷. The rotary-armature 217 is immediately attracted, and the rotary-pawl 223, engaging with the longitudinal-teeth 225, begins to rotate the shaft 153. The 10 cam 192 is, therefore, rotated away from the cam-lug 191, and the escapement-finger 189 falls against the lower escapement-tooth 187. Immediately after, the locking-arm 226 locks the shaft in its advanced position, 15 and after the wipers have been brought into engagement with the first contact of the sixth level of their respective banks, the interrupter-finger 218 then separates the interrupter-springs 219 and 220, thereby de- 20 energizing the rotary-magnet. The rotary-armature then returns to its normal position, and the private-armature, following up the rotary-armature-finger 221, allows the side-switch to pass into the third position. The interrupter-springs then re-engage, but not until after the side-switch-wiper 199 has broken away from the contact-point 202.

A guarding potential is then established 30 at the contact-point with which the private-wiper is engaged, from the ground-terminal G¹⁰, contact-point 206, side-switch-wiper 200, conductor 393, back-release-relay 139 and conductor 394, private-wiper 230 to the first 35 contact of the sixth level of the private-bank 232, and to all other private-contact-points in multiple, this being done as soon as the side-switch-wiper 200 passes into contact with the grounded contact-point 206. Also, the calling subscriber's line-conductors 123 and 122 are extended to an 40 idle "connector" when the side-switch-wipers 130 and 131 shift into contact with the contact-points 209 and 212, respectively, by way of the conductors 395 and 396, line-wipers 229 and 228 and over trunk-conductors similar to the trunk-conductors 397 and 398, which former are assumed to be idle. Should said trunk-conductors leading from 45 the first contact-terminal of the sixth level be busy, there will then be a guarding potential at the first contact-point of the sixth level of the private-bank, established thereby some occupying-switch, and over a circuit 50 similar to the one already described in connection with the side-switch-wiper 200 when the latter passed into connection with the contact-point 206. Assuming, also, that the first and the next succeeding eight trunks 55 or trunk-lines of the sixth level are busy, there will be a guarding potential not only at the first private-contact of the sixth level, but also at the second, third, etc., eighth and ninth. The wipers being opposite the first 60 contact of the sixth level, if the calling sub- 65

scriber now grounds the rotary-line-conductor 122 by pressing the button 356, the private-magnet will be energized as before, and the side-switch will be thrown into the second position. The side-switch-wiper 199, 70 upon closing with contact-point 202, at once energizes the rotary-magnet, and then the rotary-pawl 223 rotates the shaft-wipers into engagement with the first contacts of the sixth level of their respective banks, but 75 these wipers will not stop there. A circuit is closed through the private-magnet, as soon as the private-wiper 230 strikes the first busy contact-point, as follows: from the grounded terminal G⁷ of the battery B², through the switch occupying the first trunk 80 of the sixth level and circuit not shown, to the first contact-point of the sixth level of the private-bank 232, through the private-wiper 230, conductor 394, the back-release-relay 139, thence through the side-switch-wiper 200, contact-point 205 and conductors 397 and 440, the private-magnet 172, conductors 391, 386 and 382 to the non-grounded 85 terminal of battery B² to ground G⁷. The side-switch is, therefore, held in the second position by the private-armature through the medium of the tooth escapement. As soon as the interrupter-finger separates the interrupter-springs, the rotary-magnet is 90 de-energized, and the rotary-armature returns to its normal position; but the private-armature does not follow, the private-magnet being still magnetized. As soon as the interrupter-springs re-engage, the rotary-magnet is once more energized, and the side-switch-wiper 199 being still retained on contact-point 202, the shaft is rotated one 95 more step, carrying the private-wiper onto the second contact of the sixth level, which contact-point also has guarding potential. As soon as the interrupter-springs 219 and 220 are again separated by the interrupter-finger, the rotary-armature once more returns to its normal position; but still the 100 private-armature does not follow. In this way, the shaft is rotated step-by-step as long as the private-wiper continues to encounter private-contact-points with guarding potential. After the wipers are rotated 105 into connection with the ninth bank-contacts of the sixth level, the rotary-magnet is once more energized, and thus the wipers are rotated onto the tenth contact. The interrupter-springs are again separated and the rotary-armature begins once more to return 110 to its normal position. As soon as the private-wiper leaves the ninth contact of the sixth level and passes onto the tenth contact, the energizing circuit through the private-magnet is broken, and the private-armature falls against the rotary-armature-finger 221 which is still depressed. As the rotary-armature returns the private-armature also 115 returns to normal position, and the side- 120

switch passes to the third notch before the interrupter-springs again engage. At the end of this automatic rotation, a guarding potential is established at the tenth contact 5 of the sixth level, and the subscriber's line is extended over the line-wipers 229 and 228, through the trunk-conductors 397 and 398 to an idle "connector". This connection is clearly shown in Fig. 2. When the called 10 subscriber next presses the button 355 twice, the vertical-line-relay 250 of the "connector" D is energized twice by a current passing from the ground-terminal G⁶ to the ground-post 359 and over the vertical-line-conductor 15 123, side-switch-wiper 130, contact-point 209, conductor 395 to the vertical-line-wiper 229 of the "first-selector", thence through the vertical-trunk-conductor 397, the "connector-vertical-line-relay" 250, the winding 331 of 20 the differential-relay 329, thence through conductors 338, 399 and 400 to the non-grounded terminal of battery B² to ground G⁷. The armature 252 of the "connector-vertical-line-relay" 250 then presses the 25 spring 255 against ground-spring 256 twice, thus energizing the vertical-magnet 260 twice through a circuit from ground-terminal G¹¹ through springs 256 and 255, conductor 401, private-springs 278, 277, conductor 402, vertical-magnet 260 and conductor 403, through contact-point 296, thence through the side-switch-wiper 291, the conductors 404, 405 and 400 to the non-grounded terminal of battery B² and to 30 ground G⁷. Each time the vertical-armature is attracted, the shaft 259 is raised one step, and the line-wipers 312 and 313 are, therefore, raised to a level with the second row of the line-bank 311, and opposite the first 35 contact thereof. At the sub-station #220, the button 356 is next pressed, only once, and the "connector-rotary-line-relay" is energized through a circuit as follows: from ground-post 359, and over the rotary-trunk-conductor 122 to the "first-selector-side-switch-wiper" 131, through the contact-point 212, conductor 396 to the rotary-line-wiper 228, and thence over the rotary-trunk-conductor 398, through the rotary-line-relay 251 40 of the "connector", conductor 335, winding 330 of the differential-coil 239, the conductors 337 and 406, ringer-relay-springs 347 and 348, conductors 407, 405 and 400 to the non-grounded terminal of battery B² and to 45 ground G⁷. When the rotary-line-relay 251 is energized its armature 253 presses the line-relay-spring 257 against ground-spring 256, thereby closing a circuit through the private-magnet 274, from ground-terminal G¹¹ through the springs 256 and 257, conductor 408, private-magnet 274, conductors 409, 410 and 406, ringer-relay-springs 347 and 348, conductors 407, 405 and 400 to the non-grounded terminal of battery B² and to 50 ground G⁷. The private-magnet, when energized once, attracts its armature once, causing the escapement-finger 285 to disengage from the lower rearmost escapement-tooth 281 upon the downward stroke, and to fall against the upper rearmost tooth 282, 70 from which it then disengages when the private-armature returns to normal position. The side-switch then passes to the second position, and the wipers 291, 292, 293, 294 and 295 pass into engagement with the contact-points 301, 302, 303, 304 and 305, respectively. The next thing that the calling subscriber does is to press the button 355 ten times, this operation corresponding to the third digit of the number that is being 80 called. The vertical-line-conductor 123 is thus grounded ten times, and the vertical-line-relay 250 is energized ten times through the same circuit as before. Each time the springs 255 and 256 are brought together the 85 rotary-magnet 269, instead of the vertical-magnet, becomes energized through the following circuit: from ground-terminal G¹¹ through the springs 256 and 255 and conductor 401, private-springs 278 and 277, conductor 411, the rotary-magnet 269 and conductor 412, thence through contact-point 301 and the side-switch-wiper 291, the conductors 404, 405 and 400 to the non-grounded 90 terminal of battery B² and to ground G⁷. Each time the rotary-magnet is energized the rotary-armature 270 is attracted and the rotary-pawl 272 engages with the longitudinal-teeth 273 and rotates the shaft one 95 step. At the end of the tenth step the line-wipers 312 and 313 will be engaged with the tenth contact of the second level of the "connector-bank" 311 and, therefore, with the normal-conductors 421 and 422 that lead to the called subscriber's station. Then, as 100 soon as the calling subscriber presses the button 356, the rotary-trunk-conductor is grounded once, and the rotary-line-relay of the "connector" is once more energized through the same circuit as before. The 105 private-magnet is then energized again by the closing of springs 256 and 257. When the private-armature is operated, the side-switch passes to the third position by reason of the escapement-finger 285 disengaging 110 first from the tooth 284 and then from the tooth 283. As soon as the side-switch-wipers 291 and 293 close with the contact-points 306 and 308, respectively, an energizing circuit is completed through the 115 ringer-relay 344, from ground-terminal G¹² through contact-point 308, side-switch-wiper 293, conductors 413 and 414, the ringer-relay 344 and conductor 415, differential-springs 333 and 334, conductor 416, contact-point 306, thence through the side-switch-wiper 291 and conductors 404, 405 and 400 to the non-grounded terminal of battery B² and to 120 ground G⁷. Also, as soon as the ringer-relay is energized, the ringer-relay- 125 130

armature 345 then forces the ringer-relay-springs 347, 350 and 353, respectively, away from the springs 348, 351 and 354 and into engagement with the springs 346, 349 and 352. When the springs 347 and 346 close contact, sufficient energizing current is sent over the line through the calling sub-station for the purpose of energizing the talking-circuit at such place.

10 The path of this electric battery-current may be traced from ground-terminal G¹³ through the ringer-relay-springs 346 and 347, the conductors 406 and 337, and winding 330 of the differential-relay 329, the conductor 335 and rotary-line-relay 251, and thence through the rotary-trunk-conductor 398, the rotary-line-wiper 228 of the "first-selector" C, conductor 396, contact-point 212, through the side-switch-wiper 131, rotary-line-conductor 122, the spring 120 and contact-point 118, conductors 417 and 418, the primary winding 117 of the induction-coil 102, transmitter 116, contact-point 126, spring 125, the primary-circuit-springs 107 and 108 and the conductors 419 and 420, contact-point 119, spring 121 and vertical-line-conductor 123, thence through the side-switch-wiper 130 of the "first-selector" C, contact-point 209, conductor 395, the vertical-line-wiper 229, and the vertical-trunk-conductor 397, vertical-line-relay 250, conductor 336, winding 331 of the differential-relay 329, the conductor 400 to the non-grounded terminal of battery B² and to ground G⁷. After the side-switch passes to the third position, and the side-switch-wipers 293 and 291, respectively, come in contact with the contact-points 308 and 306, and after the ringing-relay is energized, and the springs 350 and 353, respectively, are pressed into contact with the springs 349 and 352, the calling line is extended to the normal-conductors 421 and 422 through the condensers 425 and 426 and conductors 424 and 427 to the line-wipers 312 and 313, by way of the side-switch-wipers 294 and 295 and conductors 423 and 428. Also, a circuit is completed through the cut-off-relay of the manual subscriber. Said circuit may be traced from ground-terminal G⁴ through the cut-off-relay 55, the vertical-trunk-conductor 421 and the vertical-line-wiper 312 of the "connector" D, conductor 423, contact-point 309, the side-switch-wiper 294 and thence through the ringer-relay-springs 350 and 349, conductor 424, the retardation-coil 339 and conductors 399 and 400 to the non-grounded terminal of battery B² and to ground G⁷. Said cut-off relay is thus energized, and the cut-off-relay-armatures 12 and 13 are attracted, thereby completing a connection between the calling subscriber's line and the desired subscriber's station over the following circuit: from the transmitter 116 through the primary winding 117 of the

induction-coil 102, over conductors 418 and 417, the rotary-line conductor 122 and the "first-selector-side-switch-wiper" 131, the contact-point 212 and conductor 396, thence through the rotary-line-wiper 228 to the trunk-conductor 398, through the condenser 426 of "connector" D, conductor 427, ringer-relay-springs 352 and 353, the side-switch-wiper 295 and the contact-point 310, thence through conductor 428, the rotary-line-wiper 313, the rotary-trunk-conductor 422, contact-point 67, the armature 13 of cut-off-relay 55 and conductor 11, through the condenser 3, the switch-hook 73 and the ringer 2, conductor 10, armature 12, contact-point 66, the vertical-normal-conductor 421, and the vertical-wiper 312 of "connector" D, conductor 423, contact-point 309, and the side-switch-wiper 294, through the ringer-relay-springs 350 and 349, the conductor 424 and the condenser 425, the vertical-trunk-conductor 397, the vertical-line-wiper 229 of the "first-selector" C, conductor 395, contact-point 209, side-switch-wiper 130, conductors 123, 420 and 419, the primary-circuit-springs 108 and 107, spring 125, contact-point 126, and again to the transmitter 116. Having completed his connection, the calling subscriber next presses the signaling or ringing-button 124. When said button is pressed, the spring 125 is separated from the contact-point 126, thereby separating the vertical-line-conductor, of which the spring 125 is a terminal, from the rotary-line-conductor, of which the contact 126 is a terminal, and grounding said vertical-line-conductor against the contact-point 127. The effect of grounding the vertical-conductor at this time is to energize the vertical-line-relay 250 of the "connector" D, and also the differential-relay 329, by energizing the coil 331. This circuit extends from the ground-terminal G⁶ through springs 109 and 110, the contact-point 127 and the signaling-spring 125, the primary-circuit-springs 107 and 108, conductors 419 and 420, the contact-point 119 and the spring 121, and thence to the vertical-conductor 123 through the vertical-line-relay 250 of the "connector" D and the winding 331 of the differential-relay 329, conductors 338, 399 and 400 to the non-grounded terminal of battery B² and to ground G⁷. The energizing of the vertical-line-relay at this time has no utility; but as soon as the differential-relay 329 is energized the armature 332 is attracted and the differential-relay-springs 333 and 334 are separated. It will be understood that these two springs are included in the energizing circuit of the ringer-relay. Therefore, when the subscriber presses the signaling-button and energizes the differential-relay, the ringer-relay is de-energized and the ringer-relay-springs resume their normal positions. The

ringer-relay-springs 350 and 353, after separating from the springs 349 and 352, re-engage with the springs 351 and 354, respectively. The ringing-current then passes 5 from the ringer-generator R to ground G⁵ and to the grounded terminal G³ of the battery B¹ of the manual exchange, through said battery and conductor 75^a, retardation-coil 74, conductor 429, ringer-relay-springs 10 351 and 350, through the side-switch-wiper 294, contact-point 309, conductor 423, the vertical-line-wiper 312 and the vertical-trunk-conductor 421, contact-point 66 and armature 12 of the manual subscriber's cut-off-relay 55, through the conductor 10, ringer 2 and the switch-hook 73, through condenser 3 and conductor 11, armature 13, contact-point 67, the rotary-normal-conductor 20 422 and the rotary-wiper 313, conductor 428, contact-point 310, through the side-switch-wiper 295, the ringer-relay-springs 353 and 354 and conductor 430 to ringer-generator R. It will be understood that the ringer-generators represented in Figs. 4 and 25 1 are one and the same machine. Also, it will be seen that when the ringer-relay is de-energized and the spring 350 separates from the spring 349, the circuit that was described as the energizing circuit of the cut-off-relay 55 is then opened. The cut-off-relay is therefore de-energized, but only for a very short period of time, for as soon as the terminals of the ringer-generator R are brought across the normal-conductors 421 and 422—when the ringer-relay-springs 350 and 353, respectively, close with the ringer-relay-springs 351 and 354—another circuit is established through said cut-off-relay. The said circuit extends from the non-grounded terminal of battery B¹ and conductor 75^a, through the retardation-coil 74, conductor 429, ringer-relay-springs 351 and 350, side-switch-wiper 294, contact-point 309, conductor 423, vertical-line-wiper 312, vertical-normal-conductor 421, cut-off-relay 40 55 to ground G⁴ and back to the grounded terminal G³ of the battery B¹. In this way, the cut-off-relay is maintained in an energized condition even while the ringing-current is being passed to the line of the desired subscriber. As soon as the calling subscriber releases the signaling-button 124, the vertical-line-relay of the "connector," and the differential-relay, again become de-energized, and the differential-relay-springs 333 and 334 again close contact with each other, thus restoring the energizing circuit of the ringer-relay. As soon as the receiver 5 is removed from the switch hook 73 of the sub-station #620, a circuit is closed through the transmitter 4 of said sub-station, which provides said transmitter with energizing-current for talking purposes. Said energizing-circuit extends from the non-grounded terminal of 45 50 55 60 65 70 75 80 85 90 95 100 105 110 115 120 125 130

the battery B² through conductors 400 and 399, the retardation-coil 339, conductor 424 and the ringer-relay-springs 349 and 350, side-switch-wiper 294, contact-point 309 and conductor 423, the vertical-line-wiper 312, normal-conductor 421, contact-point 66, armature 12, conductor 10, transmitter 4, switch-hook 73, through the retardation-coil 6, conductor 11, armature 13 and contact-point 67, the rotary-normal-conductor 422 and the rotary-wiper 313, conductor 428, the contact-point 310, conductor 431, through the back-release-relay 340, conductors 432 and 413, side-switch-wiper 293, contact-point 308 and to ground G¹². The subscribers are now in position to communicate with each other. It is evident that the receivers of the two sub-stations in communication are not connected metallically, but inductively, as the receiver of sub-station #620 is bridged across the retardation-coil 6 through the condenser 3. Now, when the subscriber at sub-station #620 talks into the transmitter 4, variations are produced in the resistance of the circuit, and in the intensity of the electric current that passes through said transmitter. These variations are transmitted through the condensers 425 and 426 to the circuit of the calling subscriber that contains the primary winding 117 of the induction-coil 102. Corresponding variations are in turn induced into the secondary winding 101 of said induction-coil and the receiver 100 in series. Therefore, when the subscriber at sub-station #620 talks into his transmitter, the subscriber at the calling sub-station can hear what is said. In turn, when the subscriber at sub-station #220 talks into his transmitter 116, variations are produced in the intensity of the current that passes through said transmitter, and these variations pass over the same circuit, through the condensers 425 and 426, and reach the receiver 5 of sub-station #620. These talking-currents, it will be understood, pass from one sub-station to another over the circuit that connects the two sub-stations, and which has been pointed out. When the two subscribers are through talking they restore their receivers to their places. If the switch-hook at sub-station #620 is drawn down first, the energizing circuit through the transmitter 4 is then broken as soon as the hook leaves the two contact-points 75 and 76, and the ringer 2 with the condenser 3 are restored in series across the line-conductors 10 and 11. Now, when the receiver 100 at sub-station #220 starts the switch-hook 103 on its downward motion, the three release-springs 112, 113 and 114 are flexed together and into contact. The rotary and vertical line-conductors 122 and 123 are thereby simultaneously grounded. The grounding of the rotary-line-con-

ductor 122 at first accomplishes nothing, since it is at this time grounded not only at the release-spring 114, but also at the ringer-relay-spring 346. Therefore, no current passes through the rotary-line-relay 251, nor through the winding 330 of the differential-relay 329, since these two coils are short-circuited through the ground. Said short-circuit may be traced from the ground-terminal G^6 at sub-station #220, through the ground-springs 109 and 110, conductors 376, release-springs 114 and 113, conductors 433, 417, spring 120, thence over the rotary-line-conductor 122 to the "first-selector-side-switch-wiper" 131, contact-point 212, conductor 396, through the rotary-line-wiper 228, the trunk-conductor 398, thence through the rotary-line-relay 251, the conductor 335, and the winding 330 of the differential-relay 229, over the conductors 387 and 406, and through the ringer-relay-springs 347 and 346 to the ground-terminal G^{13} . However, as soon as the vertical-line-conductor 123 is grounded, the vertical-line-relay 250 of the "connector" is energized, as well as the winding 331 of the differential-relay 329. As soon as the said differential-relay becomes energized, the armature 332 is attracted, and the differential-relay-springs 333 and 334 are separated. The energizing circuit through the ringer-relay 344 is thereby broken, and the ringer-relay-springs 347 and 346 return to their normal positions. At the instant that the ringer-spring 347 comes into contact with the adjacent spring 348, the rotary-line-relay 251 becomes energized, as well as the winding 330 of the differential-relay 329. Under these conditions, both of the windings of said differential-relay are energized, but the current passing through them does so in such relative directions that they simply augment each other. Therefore, the differential-relay remains energized, even after the line-relay-springs 254 and 258 come into contact, and remain so as long as both the rotary and the vertical line-relays 251 and 250 are kept energized. As soon as said springs close contact, an energizing circuit is completed through the "connector-release-magnet" 317, in series with the back-release-relay 139 of the "first-selector" C. The current passes from the grounded terminal G^7 of the battery B^2 to the ground-terminal G^{10} and to the side-switch-contact-point 206, through the side-switch-wiper 200, thence through conductor 393, back-release-relay 139 to the private-wiper 230, thence over the trunk-release-conductor 434, through the line-relay-springs 254 and 258 over the conductors 435 and 436, through the release-magnet 317, conductors 437, 410 and 406, through the ringer-relay-springs 347 and 348 and the conductors 407, 405 and 400 to the non-grounded terminal of the battery B^2 and to ground G^7 . As soon as the release-magnet 317 of the "connector" D becomes energized, the release-armature 318 moves the double-dog 266 away from the shaft and locks it with the release-link 267. The "connector-shaft" is then restored to its normal position, as well as the side-switch. At the same time that the "connector-release-magnet" 317 is energized, the back-release-relay 139 of the "first-selector" C is energized also, as was stated, and the "back-release-relay-armature" 438, upon being attracted, presses the back-release-relay-springs 140 and 141 into contact with each other. At once the "first-selector-release-magnet" 163 becomes energized by the current that passes from the grounded terminal G^7 of the battery B^2 to the ground-terminal G^{14} , through the back-release-relay-springs 141 and 140 and over the conductors 439 and 340*, through the release-magnet 163 and over the conductors 385, 386 and 382 to the non-grounded terminal of the battery B^2 and to ground G^7 . When said release-magnet 163 attracts its armature 162, the release-link 161 is thrust forward, and the double-dog-lug 165 is caught in the aperture 164, remaining so as long as said release-magnet remains energized. When the switch-hook at sub-station #220 has descended far enough, the member 115 of said hook clears the release-spring 112, and the grounding circuit to the rotary and vertical line-conductors 122 and 123 is interrupted as soon as the release springs, by reason of their own tension, regain their normal positions. The rotary and vertical line-relays 251 and 250 of the "connector" D immediately become de-energized, and their armatures 253 and 252, by returning to their normal positions, destroy the continuity of the energizing-circuit through the "connector-release-magnet" 317 and through the "first-selector-back-release-relay" 139. The armature 318 of the "connector-release-magnet" then returns to its normal position, as well as the armature 438 of the "first-selector-back-release-relay." As a result of the latter operation, the "first-selector-release-magnet" 163 lets go of its armature 162, which latter then returns to its normal position and restores the "first-selector." It is evident that should the subscriber at sub-station #220 restore his receiver first, the releasing of the "first-selector" C and the "connector" D would then take place in the manner described. But as soon as the "connector" is released, the shaft in returning to its normal position, causing the line-wipers 312 and 313 to disengage from the normal-conductors 421 and 422, would destroy the energizing-circuit through the cut-off-relay 55, and through the transmitter 4, thereby de-energizing the said relay and transmitter. The armatures 12 and 13 then return to their normal po-

sitions, resting against the contact-points 93 and 94, respectively. It has been shown, therefore, how the calling subscriber obtains his number when the way is clear; but had 5 the number 620 been busy, the "connector" would have been released when the private-magnet 274 was energized after the side-switch was in the second position. Should the manual subscriber #300 be connected 10 with the manual subscriber #620, it has been pointed out that the supervisory-relays 60 and 81 and the cut-off-relay 55 are energized, and, therefore, that the normal-conductor 422 is connected with ground G³ 15 through the supervisory-relay 81, conductors 80, 62 and 79, plug-tip 53 and a conductor 72. Now, if the rotary-line-conductor is grounded by a calling subscriber pressing the button 356 while the "connector-side- 20 switch" is in the second position, the "connector-private-magnet" 274 is then energized, and the springs 279 and 280 are closed together. As soon as they come into contact, the back-release-relay 340 of the "connector" becomes energized by a current passing 25 from the grounded rotary-normal-conductor 422 through the rotary-wiper 313, conductor 428, contact-point 310, conductor 431, back-release-relay 340, conductor 432, side-switch-wiper 293, contact-point 303, 30 conductor 441, private-springs 279 and 280, conductors 442 and 436, release-magnet 317, ringer-relay springs 347 and 348 to the non-grounded terminal of battery B² and to ground G⁷. It is evident that the energizing-circuit through the back-release-relay 340 passes through the release-magnet 317; but the magnetic force developed at the latter is not sufficient to operate the release-armature 318. This is due to the fact that 35 the number of turns of the wire wound on the electro-magnet 340 is larger than that of the same wire of the electro-magnet 317; also, to the tension of the spring against which the release-armature operates. The resistance of the black-release-relay is approximately 500 ohms, while the resistance of the release-magnet is only about 60 ohms. However, as soon as the back-release-relay 40 armature forces the springs 342 and 343 into engagement, the back-release-relay-coil is short-circuited, and the release-magnet then receives enough current to attract the release-armature. The energizing-circuit through said release-magnet is now from ground G¹⁵ through the back-release-relay springs 342 and 343, conductors 443 and 441, private-springs 279 and 280, conductors 442 and 436, through the release-magnet 317, 45 conductors 437, 410 and 406, ringer-relay-springs 347 and 348, conductors 407, 405 and 400 to the non-grounded terminal of battery B² and to ground G⁷. The short-circuiting or shunting of the back-release-relay takes 50 place through the ground-terminal G¹⁵ and the back-release-relay-springs 342 and 343, conductor 443, contact-point 303, the side-switch-wiper 293 and the conductors 413 and 432, through the back-release-relay 340, conductor 431, contact-point 310, conductor 428 and rotary-wiper 313 to the grounded normal-conductor 422. As soon as the release-magnet becomes energized, the "connector-shaft" returns to its normal position, 55 and the side-switch is moved to the first position. The calling subscriber, thinking that he has established connection, will press his signaling-button 124, thereby grounding the vertical-line-conductor, which at this stage, since the "connector" is released, has the effect of only raising the shaft "off-normal"—that is, from its normal position. As soon as this occurs, the normal-spring 444 engages with the contact-point 445, and a busy signaling-current, of a buzzing nature, is 60 thrown across the receiver. The apparatus for producing the busy-signal consists of a circuit-interrupter 446 (Fig. 2) in series with the primary winding 447 of an induction coil 448 between the non-grounded 65 terminal of the battery B² and the ground-terminal G¹⁶. The induction-coil 448 has a secondary winding 449 through which an alternating current is induced by the interruptions in the current 70 that passes through the primary winding 447. It is across the coil 449 that the receiver 100 or any other receiver that receives the busy-signal is bridged. The busy-circuit 75 extends through the secondary winding 449 of the induction-coil 448, and passes through conductor 450, the side-switch-wiper 292, contact-point 297, conductor 451, the normal-spring 444 and the contact-point 445, conductors 452 and 427, condenser 426, conductor 398, wiper 228, contact-point 212 and the side-switch-wiper 131, conductors 122, 417 and 418, primary winding 117 of induction-coil 102, the transmitter 116, contact-point 80 126, spring 125, and springs 107 and 108 over conductors 419 and 420, conductor 123, through the side-switch-wiper 130, contact-point 209, the conductor 395 and the vertical-wiper 229, conductor 397, the vertical-line-relay 250, conductor 336 and winding 331 85 of differential-coil 329, conductors 338, 399 and 400, and back to secondary winding 449 again. The calling subscriber will then 90 recognize that the number he wishes is busy, and will restore his receiver, thereby grounding both line-conductors 122 and 123 simultaneously. The grounding of these conductors, it has been pointed out, results in the simultaneous energizing of the line-relays 95 250 and 251 of the "connector" and, therefore, of the release-magnet of the "connector" and of the back-release-relay of the "first-selector" in series. It has also been 100 pointed out that whenever this occurs, the release mechanism is energized, and it is 105 130

then evident that the switches will be released. In the "connector" however, the shaft will not rotate at all when the release mechanism is operated, but will only drop straight down, since the shaft had only been raised by the pressing of the button 124, and not rotated. The manual line in question could be busy also by having been called by another automatic subscriber. In that case, the rotary-normal-trunk-conductor is connected to ground through said "occupying-automatic-connector", and through a circuit similar to the following: from ground-terminal G¹² to the contact-point 308, side-switch-wiper 293, conductors 413 and 432, back-release-relay 340, conductor 431, contact-point 310, conductor 428, rotary-line-wiper 313 to the rotary-normal-conductor 422. The side-switch of the calling "connector" being in the second position when the rotary-line-conductor is grounded, the back-release-relay 340 is energized through a circuit beginning from a ground-terminal similar to ground-terminal G¹² of the "occupying-connector", and a back-release-relay to the rotary-normal-conductor 422, as traced above, thence through the rotary-line-wiper 313, conductors 428 and 431, back-release-relay 340, conductors 432 and 413, side-switch-wiper 293, contact-point 308, conductor 441, private-springs 279 and 280, conductors 442 and 436, release-magnet 317, conductors 437, 410 and 406, ringer-relay-springs 347 and 348, conductors 407, 405 and 400 to the non-grounded terminal of the battery B² and to ground G⁷; and in this way the release-magnet 317 becomes energized, and the "connector" is released. The calling subscriber, upon pressing the signaling-button, gets the busy-signal and then restores the switches by hanging up his receiver. If, while the automatic and manual subscribers #220 and #620 are connected, a second manual subscriber #300, for instance (Fig. 1) calls for #620, the manual operator will test the line #620 by striking the jack-sleeve 57 with the calling cord-tip 53, and will get a busy click through the receiver, which will indicate that subscriber #620 is busy. When the tip 53 strikes the sleeve 57, a circuit is closed through the test-relay 453 from ground G⁸ through the test-relay 453, conductor 454, armature 62, conductor 79, contact-point 77, spring 68, tip 53, sleeve 57, conductor 56, vertical-normal-conductor 421, vertical-wiper 312 of "connector" D, conductor 423, contact-point 309, side-switch 294, ringer-relay-springs 350 and 349 to conductor 424, retardation-coil 339, conductors 399 and 400 to the non-grounded terminal of the battery B² and to ground G⁷. When the test-relay is energized, its armature 455 is attracted and drawn against the contact-point 456. This will close a circuit through the winding 457 of the induction-

coil 458, from ground G⁸ through armature 455, contact-point 456, winding 457 of induction-coil 458, conductors 459 and 75^a to the non-grounded terminal of the battery B¹ and to ground G⁸. As the operator for a moment simply touches the tip 53 to the jack-sleeve 57, the test-relay 453 will be energized just for a moment, thereby causing only a momentary flow of current through the winding of the induction-coil 458. A magnetic field is created about said winding that will induce a current in the coil 460. This latter coil is in series with the receiver 47. The circuit of the induced current is from the winding 460 of the induction-coil 458, through the receiver 47, spring 43, conductors 48 and 7, tip-spring 42 of answering-jack 31, conductor 41, armature 20, conductor 21, switch-hook 15, transmitter 23, conductor 24, armature 25, conductor 32, jack-sleeve 33, conductors 34 and 49, spring 44, contact-point 46, condenser 461, and back again to the coil 460. The two springs 43 and 44 are pressed against the contact-points 45 and 46, respectively, while the operator makes the busy-test. The operator will then inform the calling subscriber that the number is busy.

Therefore, from the foregoing, it is clear that if two manual exchange subscribers are connected, an automatic line cannot connect with either of said subscribers; nor if an automatic and a manual line are connected can a second automatic line connect with said manual line. In the latter case, also, should a second manual exchange subscriber desire connection with said engaged manual line, the operator in making a test will get the busy-click. No reference has been made to methods whereby automatic subscribers connect with automatic subscribers, or whereby manual subscribers connect with automatic subscribers, since this is not necessary to a full understanding of my invention. Any one of a number of methods may be used for such purposes, according to the requirements of different cases. My present invention comprises, it will be seen, an improved "connector" and means for connecting the jacks of the manual lines with the banks of said improved "connectors". It is evident that a desirable method of numbering the lines of the two systems would be to number the automatic lines from 100 through the fifth hundred, and the manual lines from 600 through the ninth hundred. Then, as has already been suggested by the numbering of the stations, it is clear that the first five levels of the "first-selector-banks" lead in the direction of the automatic subscribers and that the sixth to tenth levels, inclusive, lead to my improved "connectors" and thence to the manual subscribers. The above principle, as applied to one thousand

lines, can be extended indefinitely. For instance, it may be applied to systems of five thousand automatic subscribers and five thousand manual subscribers. The "connectors" from the levels just described would lead in the same direction as before, the only difference being that the "second-selectors" would have to be used between the "first-selectors" and the "connectors". In the foregoing, it is evident, therefore, that my improved "connector" comprises a side-switch, substantially as set forth, and that said side-switch, when it springs into the third position, causes the ringer-relay to be energized, that the latter by so doing closes a circuit that conveys the current for energizing the transmitter of the calling automatic subscriber, and that the current for the talking-circuit of the calling line is under the control of the ringer-relay in the "connector". Said energizing-circuit contains the vertical and rotary line-relays, as explained, and also the windings of the differential-relay on the "connector" in use. The former relays, therefore, become energized and remain so during a connection, but the differential-relay remains inactive, since the direction of the current through the windings of the latter, at such time, produce in it magnetizing forces that neutralize each other. The vertical-line-relay and one winding of the differential-coil are located between one side of the talking-circuit and the common battery, and the rotary-line-relay and the second winding of the differential-coil between the other side of said talking-circuit and said common battery. The coils, by their inherent resistance, regulate the amount of current that is maintained in the calling line when it is in use, and they also furnish impedance to prevent the flow of voice-currents through the battery B^2 . On the other hand, the circuit through which energizing-current reaches the transmitter of the called manual exchange subscriber, when an automatic line is connected with the former, comprises two normally open contact-points. One of said points is closed when the side-switch passes to the third position, after the "connector" has made connection with the called line. The other point is closed by the switch-hook at the called station when the receiver is removed from its hook and the latter is permitted to rise. In said energizing-circuit there are included two coils, the "connector-back-release-relay" and the "connector-retardation-coil". These coils are used between the battery-terminals and the talking-circuit and serve to regulate the amount of current that passes through the transmitter of the called station. The "connector-back-release-relay" is located between one side of the talking-circuit and the battery, and the retardation-coil is located between the other side of the talking-circuit and the battery B^2 . These coils also, by reason of their impedance, serve to prevent the voice-currents from short-circuiting through the battery that furnishes talking-current. Therefore, talking-current, when an automatic exchange line is connected with a manual exchange line, is furnished to the several stations through independent circuits, and from special points in the "connector". The leads from the ringer-generator are normally connected with the lower two side-switch-wipers, but become disconnected from said wipers as soon as the ringer-relay becomes energized. An important point in connection with my improved "connector" is that the release-magnet, the private-magnet, the rotary-line-relay, and the winding of the differential-relay that is in series with the latter are all, by a common lead, connected with one of the ringer-relay springs which is normally in contact with a second relay-spring that constitutes the non-grounded terminal of the battery. When the said ringer-relay becomes energized, the coils above named are disconnected from the main battery at a point between the two springs just described. Therefore, for the reason that the release-magnet among said magnets is retained disconnected from the non-grounded pole of the battery while the ringer-relay is energized, the "connector" is not released when the talking-current to the transmitter of the calling subscriber energizes the rotary and vertical line-relays of said "connector". When the ringer-relay is energized, the spring to which the above magnets are connected is shifted, as was stated, away from the non-grounded battery-spring to a second spring which is directly connected to ground. This connection to ground is between the release-magnet and the winding of the differential-relay that is in series with the rotary-line-relay, and, therefore, the private and release magnets are not included in the energizing-circuit of the calling subscriber's transmitter. When an automatic and manual line are connected, if the differential-relay becomes active, the springs that are included in the ringer-relay-circuit are separated, and the said ringer-relay becomes de-energized, thereby restoring the release-magnet and the other said magnets to the non-grounded pole of the battery. If this occurs while the rotary and vertical line-relays are energized, the "connector" is then released. And this, in fact, is what does occur, as has been explained, when the calling automatic subscriber restores his receiver. Not only is the differential-relay used as dead resistance for retardation means, and for intermediate means by which to release, but in the hands, so to speak, of the calling subscriber serves also as an

intermediate device for signaling purposes. During an ordinary connection between two automatic exchange subscribers, the release-magnet of the "connector" is in series 5 with the back-release-relay of the "first-selector", and whenever the former is energized, because the "connector-line-relays" are energized simultaneously, the back-release-relay of said "first-selector" becomes 10 energized at the same time. Therefore, both the "connector" and the "selector" are released at once. It is by means of the "connector-back-release-relays" that my improved "connectors" are released when their 15 shaft-wipers are rotated onto busy lines. It is true that the back-release-relay becomes energized when the called subscriber removes his receiver from its hook, but the energizing-current of the talking-circuit 20 thus completed is too weak to operatively magnetize said relay. The normal-conductors that lead from the "connector-banks" of my invention terminate in the jacks of manual exchange lines, the numbers of which 25 latter correspond to the location of the terminals of said normals in the "connector-banks" from which they lead. An automatic exchange subscriber in ringing a manual exchange subscriber employs the ringing-generator of the manual system, but 30 this is not essential. The ringing-current passes through the common battery at the manual station which is connected to the manual cord-circuits on the side of the answering-plug. Furthermore, in the description 35 of the "selector" and "connector" it will be understood that the aperture on the end of the release-link is far enough from the end, so that when said link is unlocked from the double-dog, and after the 40 vertical-arm falls back, the link will then rest on the top of the double-dog lug with which it normally engages. Also, in Fig. 2, the busy-signaling apparatus shown is not 45 necessarily of the particular type described, as any suitable apparatus for that purpose will answer as well. In the drawings, the various release-magnets are illustrated as having only one coil, but this has been 50 for the purpose of simplifying the illustration. In actual practice it is found that a release-magnet works better when composed of two coils both of which constitute one magnet and which operate upon 55 their corresponding release-armature. In addition, the rotary and vertical pawls of the different switches, when they reach the limit of their stroke, encounter a bumping post or guide-pin that directs the stroke of 60 the pawl in the proper direction, and at the same time limits the movement so that the shaft may not be rotated too far at each stroke.

With my improved arrangement, it will 65 be seen that the multiple-jacks allotted to

the subscriber of a manual exchange are also connected with the multiple-contacts or line-terminals of a certain number of "connectors". In other words, the line of the manual exchange subscriber is provided 70 with an answering-jack for outgoing calls, and a plurality of multiple-jacks for incoming calls—that is, calls sent out from the manual exchange subscriber's station, and calls sent into such station by the 75 manual switchboard operator; and in addition, this same manual exchange subscriber's line is provided with a plurality of "connector-bank-terminals" for use only in establishing connection with such subscriber's 80 line, and to be used only by automatic exchange subscribers in calling the manual exchange subscriber. When the "connector" makes connection with the line-terminals allotted to the manual exchange subscriber's 85 line, the cut-off-relay 55 is energized by current flowing from the battery B² through a circuit including impedance coil 339, contacts 349 and 350 of the ringer-relay, the shaft-wiper 312 and the bank-contact 311, 90 the conductor 421 and the ground connections G⁴ and G⁷. However, when the subscriber at station #220 attempts to ring the bell of subscriber at station #620, the said 95 ringer-relay is then de-energized, and at such time the cut-off-relay 55 is energized by current flowing from the battery B¹ over a circuit including the resistance 74, the conductor 429, the contacts 350 and 351 of the ringer-relay 344, the conductor 421 and 100 the ground connections G⁴ and G³. In this way, the said ringer-relay is adapted to shift the cut-off-relay 55 from one battery to the other, and from one energizing-circuit to the other, so that after the "connector" has established its connection, the 105 said cut-off-relay then remains energized regardless of whether the ringer-relay is energized or de-energized. Also, as will be seen, the differential-relay 329 is used 110 by the calling subscriber at station #220 in ringing the bell at station #620, inasmuch as this differential-relay controls the circuit of the ringer-relay 344, whereby the 115 said ringer-relay is de-energized as soon as the differential-relay is energized after the connection has been established with the called subscriber's line. In addition, the 120 said differential-relay is used by the calling subscriber at station #220 in releasing the different switches, after the two subscribers have terminated their conversation, as by hanging up the receiver 100, and thereby momentarily using the ground for short-circuiting or shunting one coil of said differential-relay in the manner explained. By reason of its many additional functions, 125 making it preferable to de-energize the ringer-relay 344 when it is desired to connect the ringer-generator R with the estab-

lished line-circuit, the said ringer-relay remains energized during the conversation between the two connected subscribers. It will also be seen that the magnet-switching 5 side-switch-wiper 291 is permanently connected with the non-grounded pole of the battery, and that the vertical and rotary magnets 260 and 269 are connected in multiple between the private-magnet-spring 277 and the contacts 296 and 301 of the said side-switch-wiper. In this way, neither the vertical nor rotary magnet is permanently connected at either terminal with the battery, the side-switch controlling the connection 10 with the non-grounded pole of the battery, and the private-magnet controlling their connection with the grounded pole of the battery. Again, it will be observed that the ringer-relay when energized 15 bridges the battery B^2 across the talking-circuit at a point to the left of the condensers 425 and 426, thus controlling the supply of talking-current to the calling subscriber's end of the line-circuit. This is brought about as soon as the "connector" 20 establishes the desired connection, and before the called subscriber answers, and at such time the same battery B^2 is also bridged across the talking-circuit at a point 25 to the right of said condensers, although at this side of the condensers there is no talking-current flowing in the talking-circuit until the subscriber responds by removing his receiver 5 from the switch-hook 73 in the manner explained. The conductor 429 and resistance 74 not only constitute a part 30 of one of the energizing-circuits of the cut-off-relay 55, but also constitute, together with the battery B^1 , a part of the ringing-circuit over which current from the generator R is employed for ringing the bell 2 at the called subscriber's station; and in this way the same ringing-generator can be used by a calling automatic exchange subscriber 35 for ringing the bell of any called subscriber, or by the operator at the manual exchange for calling any subscriber of the manual exchange; and in either case the ringing current is put on the called subscriber's line and caused to flow through a line-circuit including the battery B^1 and the ground connections G^3 and G^5 . In each case where provision is made for enabling an automatic exchange subscriber to establish 40 connection with a manual exchange subscriber's line, it will be seen that such line is, with the cut-off-relay arrangement shown, provided with a plurality of multiple-connector-contacts or terminals which are, like the spring-jacks of the manual switchboard, normally disconnected from the line. In this way, a "connector" of the character shown in Fig. 4, when employed 45 as shown and described, involves a plurality of line-terminals which are normally disconnected from their respective lines, but which are automatically connected therewith as soon as the "connector" establishes connection with the line-terminal or set of bank-contacts allotted to the called subscriber's line, providing this line has not already been made busy by connection with an operator's cord-circuit. With this arrangement, either an operator of the manual switchboard exchange or a calling subscriber of the automatic exchange can bring about the energizing of the cut-off-relay 55, and in either case the energizing is brought about automatically as soon as connection is established with one of the multiple-terminals of the line leading to sub-station #620. Furthermore, one contact of each of the multiple-connector-line-terminals allotted to line-wires 10 and 11 is permanently grounded at G^4 , whereby the cut-off-relay 55, through which these contacts are grounded, is energized as soon as any contact connected with the conductor 421 is connected in any way whatever with the non-grounded pole of the battery. Also, as explained, the conductor 422 will be grounded at G^3 if an operator's cord-circuit-plug is inserted in any of the multiple-jacks allotted to a line leading to sub-station #620. When thus grounded, connection cannot be established with the conductor 422 by the rotary-shaft-wiper of the "connector" without instantly energizing the release-relay 340, and thereby effecting a closure of the release-circuit including the release-magnet of the "connector" and the release-relay of the "selector", as previously explained. With the arrangement shown, all current for switching, signaling and talking purposes is supplied from the common batteries, while only the current for ringing the subscribers' bells is derived from the alternating current generator R . 50

It will be seen that the back-release-relay 340 is only used for effecting the busy-release of the "connector", as this relay cooperates with the ringer-relay and the private-magnet in accomplishing the automatic release of the "connector". The line-relays of the "connector" cooperate with the ringer-relay in controlling the other energizing-circuit of the release-magnet. In this way, the said release-magnet 317 of the "connector" has two energizing-circuits, one being under the control of the calling subscriber, and the other being automatically controlled by the release-relay 340 in the manner explained. 55

It will be readily understood that the line-terminals of the "connector" may be connected with multiple line-terminals in other "connectors", and that the line-terminals of the "selector" may likewise be connected in multiple with corresponding line-terminals of other "selectors". It will also 60

be understood that any suitable or desired number of subscribers' lines may be employed, and that the exchange apparatus may involve any suitable or desired number 5 of trunk-lines or other similar connections. The resistances of the various windings of the relays, magnets and impedance-coils can be easily adjusted or changed to suit the requirements of different cases, and in such 10 manner as to obtain the desired results, and produce the herein described methods of operation.

One of the important features of my invention is the two-wire character of the 15 "connector," it being observed that in my improved "connector," as herein set forth, there are only two parallel conducting-paths, and that over these two conducting-paths all of the various required operations 20 are performed, thus making it unnecessary to have more than two wipers on the switch-shaft, and unnecessary to have anything in the "connector-banks" except the line-terminals or contacts which are actually connected with the subscribers' lines. In this 25 way, and regardless of the character of the switching machine, it will be seen that my invention contemplates broadly the establishment of a guarding potential at the line-terminal itself, and over a portion of the talking-circuit, in order to afford a busy-release or other energizing circuit, rather than at an additional contact and over a third conductor. With the "connector" 30 thus operated on a "two-wire" basis, so to speak, the construction and installation is comparatively simple and inexpensive.

When the "connector" is in use, the 35 ringer-relay 344 and the release-relay 340 are temporarily connected to ground at G¹². At such time, the ringer-relay is, of course, energized, while the said release-relay is short-circuited by the grounds G¹² and G⁷. In this way, the release-relay cannot be 40 energized while the "connector" is in use—that is, while the side-switch of the "connector" is retained in third position.

It will be seen that the answering-jack of the line running to substation #620 is 45 connected in multiple with the connector terminals 311 corresponding to said line. With this arrangement the automatic connector-switch can be used for connecting with and calling over the line independently of the jack or jacks allotted to said line. Furthermore, the said jack or jacks can be used for manually connecting with and calling over the said line independently of the automatic connector-switch. The 50 automatic connector and manual switchboard are, therefore, connected in multiple, and preferably both the switch and the manual switchboard are normally disconnected from the manual telephone line—that is to 55 say, the jacks and the connector terminal 60

are not normally in operative relation to said line. The answering-jacks will, of course, be equal in number to the total number of manual subscribers, but the number of connectors for enabling the automatic subscribers to call the manual subscribers may be less than the said total number of manual subscribers. For example, the total number of connectors may be a small percentage of the total number 75 of automatic and manual subscribers. With the arrangement shown the special connectors are employed only in automatically calling manual subscribers, and one or more 80 levels can be reserved for these connectors in the line banks of the first-selectors. Ordinary or suitable connectors are then employed for giving service between automatic subscribers. When automatic subscribers call automatic subscribers the connections are made through the medium of the unreserved levels in the first-selectors. For large exchanges it will also be understood, of course, that second-selectors and possibly third-selectors will be necessary or 85 desirable. As illustrated, first-selectors are employed as individual switches for the automatic subscribers, making the total number of first-selectors the same as the total number of automatic subscribers. It will 90 also be understood, however, that the first-selectors may be reduced in number and placed upon a percentage basis by the use of any suitable or well-known arrangement, 95 which is very common.

What I claim as my invention is:

1. A telephone system comprising a plurality of automatic exchange subscribers' lines, a plurality of manual exchange subscribers' lines, electrically-propelled and step-by-step-actuated switching machinery normally under the control of the automatic exchange subscribers, and operators' cord-connecting apparatus, each manual exchange subscribers' line being provided with a 110 spring-jack, and said switching machinery including a plurality of terminals each of which is allotted to one of said manual exchange subscribers' lines, the said terminals being connected in multiple with said jacks. 115

2. A telephone system comprising a plurality of manual exchange subscribers' lines, a plurality of spring-jacks allotted to each line, an automatic subscribers' line, an electrically-propelled and step-by-step-actuated "connector," together with means for supplying all necessary current, said "connector" being controllable at will from said automatic subscribers' line and provided with a plurality of terminals each allotted to one 120 of said lines, the said terminals being connected in multiple with said jacks. 125

3. A telephone system comprising a subscribers' line, a common source of talking current for connection with said line, a plu- 130

rality of manual switchboard spring-jacks or multiple line-terminals allotted to said line, a plurality of bank-contacts or automatic switching machine line-terminals allotted to said line for use when said line is being called, the two groups of line-terminals thus provided being connected in multiple, and means for connecting with said bank contacts at will.

10 4. A telephone system comprising a subscriber's line, a two-way spring-jack for said line, an operator's two-way cord-circuit provided with a two-way plug adapted for insertion in said jack, a battery bridged across the talking strands of the cord-circuit and grounded at one pole, a "connector" provided with a line-terminal corresponding to said subscriber's line, and a busy-release-circuit for insuring an automatic release 75 of the "connector" if the cord-plug is in the jack when the "connector" is actuated to a position corresponding to the said line, said automatic release-circuit including said ground and a talking strand of the cord-circuit.

5. A telephone system comprising a subscriber's line and a manual switch-board provided with multiple line-terminals, a common source of talking current for connection with said line, automatic switching machinery provided with multiple line-terminals, for extending a calling connection to said line, suitable connections by which the line-terminals of the manual switchboard 80 are multiplied together with the multiple line-terminals of the automatic switching machinery, and means for connecting with said terminals at will.

6. In a system of trunking between automatic and manual telephone exchanges, the combination of a plurality of automatic exchange subscribers' lines, a plurality of manual exchange subscribers' lines, electrically-propelled and step-by-step-actuated switching machinery under the control of the automatic exchange subscribers, and operators' cord-connecting apparatus, each manual exchange subscriber's line being provided with a spring-jack, and said switching machinery including a plurality of terminals each of which is allotted to one of said manual exchange subscribers' lines, the system also comprising suitable provisions whereby talking-current is supplied to a calling automatic exchange subscriber's station as soon as connection is established with a called manual board subscriber's station, but whereby the said called station does not receive talking-current until the manual board subscriber 95 answers.

7. The combination, in a system of automatic trunking from an automatic to a manual telephone exchange, of a plurality of automatic exchange subscribers' lines, a plurality of manual exchange subscribers' lines,

electrically-propelled and step-by-step-actuated switching machinery under the control of the automatic exchange subscribers, and operators' cord-connecting apparatus, each manual exchange subscriber's line being provided with a spring-jack, and said switching machinery including a plurality of terminals each of which is allotted to one of said manual exchange subscribers' lines, the system also comprising switches and means by which a calling automatic exchange subscriber can produce an audible call-signal at the station of a called manual board subscriber, and other switches by which portions of the same means can be employed by a manual board operator for producing an audible call-signal at the called subscriber's station.

8. In a system of trunking between automatic and manual telephone switchboards, the combination of a plurality of automatic exchange subscribers' lines, a plurality of manual exchange subscribers' lines, electrically-propelled and step-by-step-actuated switching machinery under the control of the automatic exchange subscribers, and operators' cord-connecting apparatus, each manual exchange subscriber's line being provided with a spring-jack, and said switching machinery including a plurality of terminals each of which is allotted to one of said manual exchange subscribers' lines, the system also comprising signaling apparatus by which a calling manual board subscriber can signal the manual board operator for a connection, and afterwards for a disconnection, together with means whereby a calling automatic exchange subscriber may transmit electrical impulses suitable for calling and ringing the manual board subscriber.

9. A telephone system comprising a subscriber's line, a "connector" for making connection with the line, a spring-jack allotted to the line, an operator's cord-circuit provided with a plug adapted for insertion in said jack, a relay for controlling the connection between the said line and the jack, and also between the line and the "connector", a battery for operating the "connector", and another battery bridged across the cord-circuit, together with two energizing-circuits for said relay, one circuit including the "connector-battery" and the other the cord-circuit-battery, said "connector" being provided with a relay controlling both of said circuits.

10. A telephone system comprising a subscriber's line, a "connector" for making connection with the line, a spring-jack allotted to the line, an operator's cord-circuit provided with a plug adapted for insertion in said jack, a relay for controlling the connection between the said line and the jack, and also between the line and the "connector", a battery for operating the "connec-

tor", and another battery bridged across the cord-circuit, together with two energizing-circuits for said relay, one circuit including the "connector-battery" and the 5 other the cord-circuit-battery, and a ringing-generator, said "connector" having a ringer-relay for controlling the flow of ringing-current from the said generator to the subscriber's line, when the "connector" is connected therewith, said ringer-relay being also 10 adapted to control both of said energizing-circuits.

11. A telephone system comprising an automatic exchange subscriber's line, a manual exchange subscriber's line, the two lines being temporarily connected for conversational purposes, and a "connector" through the medium of which the said lines are connected, together with a source of talking-current, said "connector" having a relay adapted to control the flow of talking-current to both of said subscribers' lines.

12. A telephone system comprising an automatic exchange subscriber's line, a source of talking-current, a source of ringing-current, and a "connector" provided with a ringer-relay adapted when energized to establish the supply of talking-current to the said subscriber's line.

13. A telephone system comprising a subscriber's line, a relay individual to said line, a "connector" for making connection with the said subscriber's line, said "connector" having a pair of shifting switch-contacts for the voice-currents, and an energizing-circuit for said relay, adapted to energize the latter when the line is seized, said circuit including one of said talking-contacts of the "connector."

14. A telephone system comprising a "connector" provided with talking-conductors, an operator's cord-circuit provided with talking-conductors, and an operator's busy-test-circuit, said busy-test-circuit including talking-conductors of both the "connector" and the operator's cord-circuit.

15. A telephone system comprising a "connector" provided with voice-current-conductors, an operator's cord-circuit, and an operator's busy-test-circuit, said busy-test-circuit including one of the voice-current-conductors of the "connector."

16. A telephone system comprising a "connector" provided with a pair of movable switch-contacts included in the path of the voice-currents, a release-relay for the "connector," said relay having one terminal permanently connected with one of said switch-contacts.

17. A telephone system comprising a "connector" having release mechanism operated by a release-magnet, a ringer-relay for the "connector," and an energizing-circuit for said magnet, the said circuit being controlled by said relay.

18. A telephone system comprising a "connector," a pair of line-relays, a ringer-relay, a source of talking-current, a source of ringing-current, and suitable connections whereby the ringer-relay when energized is adapted to connect the line-relays in series with the source of talking-current, and to connect the said relays in parallel when de-energized. 70

19. A telephone system comprising a line-circuit, a "connector" provided with a pair of line-relays and also with a release-magnet and a ringer-relay, a source of talking-current, a source of ringing-current, and suitable connections whereby the ringer-relay controls the supply of both talking and ringing current to the line-circuit, said ringer-relay being adapted when energized to connect the two line-relays in series with the source of talking-current, and when de-energized to connect the source of ringing-current with the line-circuit, and the source of talking-current with the line-relays in parallel, together with an energizing-circuit for the said release-magnet, said energizing-circuit being controlled by the ringer-relay. 80 85

20. A telephone system comprising a "connector" having a double-wound relay adapted to be energized when its coils are connected in parallel, and adapted to remain de-energized when its two coils are connected in series, a line-circuit, a battery for supplying talking-current through the said coils to the line-circuit, and a ringer-relay for the "connector," together with an energizing-circuit for the ringer-relay, said energizing-circuit being controlled by said double-wound relay. 90 95 100

21. A telephone system comprising a "connector" provided with a plurality of side-switch and shaft wipers, and a back-release-relay for said "connector," said relay having one terminal of its coil permanently connected with one of said side-switch-wipers. 105

22. A telephone system comprising a "connector" provided with a pair of line-relays, a double-wound relay, an impedance-coil, a back-release-relay, and a ringer-relay, a line-circuit, condensers in the said line-circuit, a suitable battery, suitable connections for supplying talking-current from the battery through windings of the line-relays and the double-wound relay to the line-circuit at one side of said condensers, and for supplying talking-current through windings of the impedance-coil and the back-release-relay to the line-circuit at the other side of the condensers, said supply of talking-current through the said coils or windings being controlled by the said ringer-relay. 110 115 120

23. A telephone system comprising an operator's cord-circuit provided with a ringing-key, a battery bridged across the cord-circuit, a "connector" provided with a ringer-relay, a ringing-generator, a subscriber's 130

line, means whereby ringing-current is projected onto the line when the ringer-relay is operated, and means whereby ringing-current is transmitted through the said battery 5 to the line when the operator's ringing-key is pressed.

24. A telephone system comprising a "connector" provided with a back-release-relay and a release-magnet, a busy-release energizing circuit for said relay, the said release-circuit including the windings of said relay and magnet in series, an independent energizing circuit for the magnet, controlled by the relay, and means for automatically 10 closing the busy-release circuit if the called subscriber is busy.

25. A telephone system comprising a "connector" provided with release mechanism operated by a release-magnet, a ringer-relay, a private-magnet, and a release-relay, together with an energizing-circuit for said release-magnet, said circuit being controlled by the private-magnet and release-relay and the ringer-relay.

26. A telephone system comprising a "connector" provided with a pair of line-relays, a release-magnet, a release-relay, a ringer-relay, and two energizing-circuits for said release-magnet, one of said circuits 30 being controlled conjointly by the line-relays and the ringer-relay, and the other circuit being controlled conjointly by the release-relay and the ringer-relay.

27. A telephone system comprising a "connector" provided with a pair of line-relays, a private-magnet, a release-magnet, a release-relay, and a ringer-relay, together with two energizing-circuits for said release-magnet, one of said energizing-circuits 40 being controlled conjointly by the line-relays and the ringer-relay, and the other circuit being controlled conjointly by the release-relay, the private-magnet and the ringer-relay.

28. A telephone system comprising a subscriber's line, a "connector" for making connection with the line, a spring-jack allotted to the line, an operator's cord-circuit provided with a plug adapted for insertion in 50 said jack, a relay for controlling the connection between the said line and the jack, and also between the line and the "connector", a battery for operating the connector, and another battery bridged across 55 the cord-circuit, together with two energizing-circuits for said relay, one circuit including the "connector-battery" and the other the cord-circuit-battery, said "connector" being provided with a relay controlling 60 both of said circuits, the system also comprising signaling apparatus by which a calling manual board subscriber can signal the manual board operator for a connection, and afterwards for a disconnection, together with means whereby a calling auto-

matic exchange subscriber may transmit electrical impulses suitable for calling and ringing the manual board subscriber.

29. A telephone system comprising a temporarily established talking-circuit, a temporarily energized ringer-relay, a release-relay having one terminal connected with one terminal of the ringer-relay, and means whereby the two relays are temporarily grounded at a point between them. 75

30. A telephone system comprising a temporarily established talking-circuit, a "connector" through the medium of which said talking-circuit is temporarily maintained, and means for supplying all necessary current, said "connector" being provided with a ringer-relay and a release-relay, the windings of said relay being connected in series and temporarily grounded at a point between them. 80

31. A telephone system comprising a plurality of lines each provided with multiple line-terminals, electrically-propelled and step-by-step-actuated switching machinery cooperating with said line-terminals, means including a portion of the talking circuit for establishing a positive or grounded guarding potential at all multiple line-terminals of any line which is in use, whereby the switching machinery is prevented from interfering with a busy line, and means for automatically trunking to said machinery. 85

32. In a telephone system, a plurality of subscribers' lines, means including a selector and a connector switch for establishing 100 connection between two of said lines, said connector switch including a talking wiper, and a busy test circuit including said wiper.

33. A combined manual and automatic telephone system comprising a plurality of 105 telephone lines, part provided with manual and part with automatic substation equipment, automatically operated link-circuit apparatus under the control of said automatic substation equipment for establishing 110 connection for conversational purposes between an automatically equipped calling line and any other desired line, and means for automatically indicating to the calling subscriber the busy condition of any called 115 line sought to be automatically connected.

34. A combined manual and automatic telephone system comprising a plurality of telephone lines, part provided with manual and part with automatic substation equipment, multiply connected spring jacks and multiply connected switch contacts for each of said manually equipped lines, link-circuits and connecting plugs for manually establishing connection for conversational 120 purposes between manually equipped lines, means for indicating to the operator the busy condition of a called line sought to be thus connected, automatic interconnecting means comprising a pair of wiper contacts 125 130

for engaging a pair of the said switch contacts of a called manually equipped line to establish conversational connection therewith, and means for indicating to a calling subscriber at an automatically equipped substation the busy condition of the called line sought to be thus automatically connected.

35. A combined manual and automatic telephone system comprising a plurality of telephone lines, part provided with manual and part with automatic substation equipment, multiply connected spring jacks and multiply connected switch contacts for each of said manually equipped lines, link-circuits and connecting plugs for manually establishing connection for conversational purposes between manually equipped lines, means for indicating to the operator the busy condition of a called line sought to be thus connected, automatic interconnecting means comprising a pair of wiper contacts for engaging a pair of said switch contacts of a called manually equipped line to establish conversational connection therewith, and means dependent upon the electrical condition of the encountered pair of contacts to indicate to a calling subscriber at an automatically equipped substation the busy condition of the called line sought to be thus automatically connected.

36. A combined manual and automatic telephone system comprising a plurality of telephone lines, part provided only with manual and part only with automatic substation equipment, electrically actuated link-circuit apparatus for automatically completing connection for conversational purposes between an automatically equipped calling and a manually equipped called line, and means for automatically restoring the interconnecting apparatus to normal at the end of conversation.

37. A combined manual and automatic telephone system comprising a plurality of telephone lines, part provided only with manual and part only with automatic substation equipment, line signals associated with the manually equipped lines and normally under the control of the subscribers, electrically actuated link-circuit apparatus for automatically completing connection for conversational purposes between an automatically equipped calling line and a manually equipped called line, and means actuated during the establishment of said connection to destroy the substation control of the called line signal.

38. A combined manual and automatic telephone system comprising a plurality of telephone lines, part provided with manual and part with automatic substation equipment, automatically operated link-circuit apparatus under the control of said automatic substation equipment for establish-

ing connection for conversational purposes between an automatically equipped calling line and any other desired line, a central source for supplying talking current to the substations of connected lines, and means for automatically indicating to the calling subscriber the busy condition of any called line sought to be automatically connected.

39. A combined manual and automatic telephone system comprising a plurality of telephone lines, part provided with manual and part with automatic substation equipment, automatically operated link-circuit apparatus under the control of said automatic substation equipment for establishing connection for conversational purposes between an automatically equipped calling line and any other desired line, a central source for supplying talking current to the manually equipped substation thus connected, and means for automatically indicating to the calling subscriber the busy condition of any called line sought to be automatically connected.

40. A combined manual and automatic telephone system comprising a plurality of telephone lines, part provided with manual and part with automatic substation equipment, line signals associated with the manually equipped lines normally under the control of the subscribers, electrically actuated link-circuit apparatus for automatically completing connection for conversational purposes between an automatically equipped calling line and a manually equipped called line, and electrically actuated means operated by current over a portion of the talking circuit thus established to destroy the substation control of the called line signal.

41. A telephone system, including a subscriber's line provided with means for initiating calls, multiple called terminals for said line, operator controlled means for connecting with terminals of said line, subscriber controlled automatic means for connecting with terminals of said line as a called line, and a trunk release circuit for said automatic means separate from the talking circuit.

42. In a telephone system, a subscriber's line provided with automatic equipment and with manual equipment, operator controlled means for seizing said line through the medium of its manual equipment, subscriber controlled means for seizing said line as a called line through the medium of its automatic equipment, and trunk release circuits for said subscriber controlled means.

43. In a telephone system, a called subscriber's line, multiple contacts for said line terminating in automatic equipment and in manual equipment, subscriber controlled automatic trunking means for seizing said line and for making all of said multiple contacts

- test busy, and a trunk release circuit for said automatic trunking means.
44. In a telephone system, a subscriber's line, line conductors therefor, branches for said line conductors normally disconnected from the line terminating in spring jacks and terminals, operator's equipment for connection with said line via said spring jacks, an automatic connector switch having access 10 to said terminal, said switch directly controlled from an automatic subscriber's line to connect with said terminals, means for connecting said normally disconnected branches with the subscriber's line, said 15 means operated over one of the line conductors of a branch.
45. In a telephone system, a subscriber's line, spring jacks normally disconnected from said line, and line terminals also normally disconnected therefrom, operator's 20 equipment for connecting with said spring jacks, an automatic connector switch directly controlled from another subscriber's line to connect with said line terminals, line 25 and test wipers for said connector switch, a relay for connecting said jacks and line terminals to said subscriber's line, said relay energized over one of the line wipers of said 30 automatic switch.
46. In a telephone system, a line, a jack and line terminals normally disconnected from the line, means for connecting said jack and line terminals with the line, another line, an automatic switch controlled 35 from said other line in response to impulses corresponding to digits of the called number for connecting with said line terminals, said means controlled over a line conductor of said line for connecting the line with the 40 jack and line terminals.
47. In a telephone system, a line, terminals for said line for manual connection therewith and terminals for automatic connection therewith normally disconnected 45 from the line, a relay for connecting said terminals to the line, an automatic connector switch for connection with said automatic terminals, means for operating said connector to seize and signal said line, a circuit for 50 said relay including a wiper of said connector, closed when the line is seized and another circuit closed in said switch while the line is being signaled for holding said relay energized.
48. In a telephone system, a calling line, a called line, an automatic progressively movable connector switch controlled from the calling line in response to impulses corresponding to digits of a called number for 55 extending a talking circuit to the called line, a normally open connection from the called line to said connector switch, a relay for closing said connection and a circuit for said relay closed over a portion of said talking 60 circuit.
49. In a telephone system, a line, a jack for manual connection with the line and terminals for automatic connection therewith, said jack and terminals normally disconnected from the line, a relay energized when 70 connection is made with the terminals for connecting said line thereto, a connector for seizing said line, a circuit closed from the connector for energizing said relay and supplying a busy potential on the jack, means 75 in the connector for projecting signaling current over the line and another circuit substituted for said first circuit to hold said relay energized and maintain a busy potential at the jack when the signaling current 80 is projected over the line.
50. In a telephone exchange system, the combination of a subscriber's line, an automatic electrically-propelled and step-by-step-actuated switch, means by which the 85 subscriber operates the switch over the line in automatically establishing connection with some other line, a spring jack allotted to said other line, an operator's connecting cord provided with a plug adapted for insertion in said jack, a subscriber's telephone, and a centralized source of talking current connected for supplying current over the 90 subscriber's line to charge said telephone.
51. In a telephone exchange system, the 95 combination of a subscriber's line, an automatic electrically-propelled and step-by-step-actuated switch, means by which the subscriber operates the switch over the line in automatically establishing connection 100 with some other line, a spring jack allotted to said other line, an operator's connecting cord provided with a plug adapted for insertion in said jack, said jack being normally disconnected from said other line, and 105 means for automatically connecting the jack with said other line when a manual connection is made therewith.
52. In a telephone exchange system, the 110 combination of a subscriber's line, an automatic electrically-propelled and step-by-step-actuated switch normally accessible automatically from said line, means by which the subscriber operates the switch over the line in automatically establishing connection 115 with some other line, a spring jack allotted to said other line, an operator's connecting cord provided with a plug adapted for insertion in said jack, a second subscriber's line, multiple jacks allotted to said second subscriber's line, a visual call-signal allotted to said second subscriber's line, and an operator's connecting cord provided with a plug adapted for insertion in the answering jack of said second subscriber's line, all 120 of said jacks mounted on the same board.
53. In a telephone exchange system, the 125 combination of a subscriber's line, a spring jack allotted to said line, a bridge normally across said line, a bridge-cut-off relay, 130

means for connecting the jack with the line when said relay is energized, a connector bank terminal allotted to said subscriber's line, and suitable instrumentalities for supplying talking current through either the jack or the connector bank terminal to the subscriber's line.

54. In a telephone exchange system, the combination of a subscriber's line, a spring 10 jack allotted to said line, a bridge normally across said line, bridge-cut-off relay, means for connecting the jack with the line when said relay is energized, a common battery, a connector bank terminal allotted to said 15 line, a pair of connector relay coils for feeding talking current through the said bank terminal to the subscriber's line, and means by which talking current is also supplied to the line when manual connection is established therewith through the medium of said 20 jack.

55. A telephone exchange system comprising a series of spring jacks, an automatic switch provided with a corresponding series 25 of terminals, a series of lines common to both the jacks and the said automatic switch terminals, each line having allotted to it a jack and an automatic switch terminal, the jack and automatic switch terminal of each 30 line occupying unlike positions in their respective series.

56. A telephone exchange system comprising a called line having multiple jacks, a connector for establishing connection with the line independently of said jacks, operators' cords and plugs for establishing connection with the line through the medium of said jacks, a back-bridge relay for said connector, and means for establishing a 40 guarding or testing potential through the winding of said relay to the said jacks.

57. A telephone exchange system comprising a called line having multiple jacks, a connector for establishing connection with the line independently of said jacks, operators' cords and plugs for establishing connection with the line through the medium of said jacks, a back-bridge-relay for said connector, and means including a ringer relay 45 for establishing a guarding or testing potential through the winding of said back-bridge relay to the said jacks.

58. A telephone exchange system comprising a called line having mutiple jacks, a connector for establishing connection with the line independently of said jacks, operator's cords and plugs for establishing connection with the line through the medium of said jacks, a back-bridge relay for said 55 connector, and means including a relay individual to said called line for establishing a guarding or testing potential through the winding of said back-bridge relay to the said jacks.

65. 59. A telephone exchange system com-

prising a subscriber's telephone line, multiple jacks allotted to said line, connector bank terminals allotted to said line, cords provided with plugs adapted for insertion in said jacks, and suitable instrumentalities 70 for establishing a negative potential at the jacks and a positive potential at the connector terminals when an operator plugs into one of said jacks.

60. A telephone exchange system comprising a subscriber's telephone line, multiple jacks allotted to said line, connector bank terminals allotted to said line, cords provided with plugs adapted for insertion 75 in said jacks, and means for establishing a potential of one polarity at the jacks and a potential of opposite polarity at the connector terminals when an operator plugs into one of said jacks.

61. A telephone exchange system comprising a subscriber's telephone line, multiple jacks allotted to said line, connector bank terminals allotted to said line, cords provided with plugs adapted for insertion 80 in said jacks, suitable instrumentalities for establishing a negative potential at the jacks and a positive potential at the connector terminals when an operator plugs into one of said jacks, and means for supplying talking current through the jacks and connector terminals to the said line.

62. A telephone exchange system comprising a subscriber's telephone line, multiple jack allotted to said line, connector bank 85 terminals allotted to said line, cords provided with plugs adapted for insertion in said jacks, means for establishing a potential of one polarity at the jacks and a potential of opposite polarity at the connector 90 terminals when an operator plugs into one of said jacks, and means for supplying talking current through the jacks and connector terminals to the said line.

63. In a telephone system, the combination 95 with a telephone line, of multiple jacks and multiple automatic connector contacts for said line, a cut-off relay for the line and means to actuate said cut-off relay either by the establishment of a manual connection with said multiple jacks or by the establishment of an automatic connection with said multiple automatic connector contacts, and means to place battery potential upon the test contacts of the multiple jacks and ground potential upon the automatic connector contacts by the establishment of either of said connections.

64. In a telephone system, a subscriber's line, an automatic connector switch provided with terminals normally disconnected from said line, and a cut-off relay connected to one of said terminals for controlling the connection of said line to said terminals.

65. 65. In a telephone system, a subscriber's

- line, a line relay normally connected to said line, an automatic connector switch provided with normal connections normally disconnected from said line, and a cut-off relay connected to one side of said normal connections for disconnecting said line relay from said line and connecting the two sides of said line to said normal connections. 66. In a telephone system, a subscriber's line, an automatic connector switch provided with terminals normally disconnected from said line, a cut-off relay connected to one of said terminals for controlling the connection of said line to said terminals, and a spring jack connected in multiple with said terminals.
67. In a telephone system, a subscriber's line, a line relay normally connected to said line, an automatic connector switch provided with normal connections normally disconnected from said line, a cut-off relay connected to one side of said normal connections for disconnecting said line relay from said line and connecting the two sides of said line to said normal connections, and a spring jack connected in multiple to said normal connections.
68. In a telephone system, a subscriber's line, a cut-off relay for said line, an automatic connector switch for seizing said line for establishing a talking connection therewith, means controlled by said cut-off relay for controlling said talking circuit, and means for controlling said cut-off relay over the talking circuit.
69. A common battery automatic telephone exchange system comprising a temporarily established talking circuit extending between the calling and called subscribers, a centralized source of talking current, and a centralized source of ringing current, together with a ringer-relay controlled by the calling subscriber and adapted when deenergized to cause ringing current to flow to the called subscriber's station, said ringer-relay being adapted to remain energized during conversation between two subscribers to preserve the continuity of both sides of the talking circuit and to control the supply of talking current to the line-circuit.
70. A telephone system comprising an automatic exchange subscriber's line, a source of talking current, a source of ringing current, and a connector provided with a ringer-relay adapted to control the supply of talking current to the said subscriber's line, the said connector having a busy-release-circuit controlled at one point by said ringer-relay.
71. A telephone system comprising a subscriber's line, a centralized source of talking current, a centralized source of ringing current, and a connector provided with a ringer-relay adapted to control the supply of both talking and ringing current to the said line, the said connector having a busy-release-circuit controlled at one point by said ringer-relay.
72. In a telephone system, a calling mechanism adapted to come to rest after each digit of the called number, an automatic switch adapted to respond to electrical impulses representing the last two digits of any called number, a ringer relay controlling the flow of ringing current to the called subscriber, and means for keeping said relay energized to maintain the continuity of the connection between the calling and called lines.
73. In a telephone system, a calling mechanism adapted to come to rest after each digit of the called number, an automatic switch adapted to respond to electrical impulses representing the last two digits of any called number, a ringer relay for said automatic switch, means for projecting ringing current onto the called line when the ringer relay is de-energized, and a circuit for keeping the said relay energized to maintain the continuity of connection between the calling and called lines.
74. In a telephone system, a ringer relay controlling the flow of ringing current to the called subscriber's line and controlling both sides of the talking circuit, a central source of talking current for supplying current to the called line for talking purposes, and a circuit for keeping said relay energized to disconnect the ringing current and to maintain the flow of talking current to the called line.
75. In a telephone system, a ringer relay common to a plurality of lines, means for connecting the contacts of said relay with any idle line, means for projecting ringing current onto any selected non-busy line by the de-energizing of said relay, and a local circuit for keeping said relay energized to close the talking circuit and maintain the flow of talking current to the called line during conversation.
76. In a telephone exchange system, a line circuit, switches adapted for both vertical and rotary movements, vertical and rotary relays bridged across the circuit, a battery having one pole grounded and the other pole normally connected with the bridge at a point between said relays, and another relay for disconnecting the rotary relay and reconnecting it with the grounded pole of the battery to include the latter in series between the two relays of the bridge.
77. In a telephone exchange system, a line circuit, switches adapted for both vertical and rotary movements, vertical and rotary relays bridged across the circuits, a battery having one pole grounded and the other pole normally connected with the bridge at a point between said relays, an-

other relay for disconnecting the rotary relay and reconnecting it with the grounded pole of the battery to include the latter in series between the two relays of the bridge, 5 and a subscriber's station receiving talking current from the said battery when the latter is thus bridged across the circuit.

78. In a telephone system, subscribers' lines and trunk lines divided into groups, automatic switches having one motion to select 10 groups and a second motion to connect with a line in the selected group for extending

a connection from a calling line to a called line, a plurality of bridges across the conductors of the talking circuit, said bridges including operating elements for said automatic switches, means for automatically reducing the number of said bridges, and means in one of said switches controlled only by the calling subscriber for supplying talking current to the calling line. 15

Signed by me at Chicago, Cook County, Illinois, this 12th day of September, 1905.

TALBOT G. MARTIN.
